METHOD OF AND APPARATUS FOR
BUILDING TIRESWalter J. Breth, Akron, Ohio, assignor to The
General Tire & Rubber Company, Akron, Ohio,
a corporation of Ohio

Application September 22, 1939, Serial No. 296,110

59 Claims. (Cl. 154—14)

This invention relates to a method of and apparatus for building tires, and more particularly to improvements in the method of and apparatus for building pneumatic tires by what is known as the flat band process.

In building or assembling pneumatic tires by the so-called flat band process, ply material consisting of diagonally disposed parallel cords embedded in the sheet rubber, is wrapped or placed about the substantially cylindrical outer surface of a drum or building form, and the circumferential marginal edges of the ply material are folded radially inward over the ends of the drum or form. Circular, inextensible beads are placed against the inturned edges of the ply material and the inturned edges are then folded about the beads to retain the latter in place. Additional ply material is then placed or wrapped about the first layer or layers of ply material on the drum or form, to build up the body of the tire in a laminated construction. This addition of extra layers of the ply material may be repeated until as many laminations of the ply material have been incorporated in the body of the tire as desired. The circumferential marginal edges of the layers of ply material are preferably folded about the beads so that the diagonally disposed cords embedded in the rubber of the ply material have their ends wrapped or secured around the beads.

According to present methods of manufacture, the successive layers of ply material are compacted or stitched together by means such as discs which are pressed against the ply material and rolled about the circumference of the drum or form, thus subjecting the ply material to localized pressure and effecting adhesion of the ply material layers. The folding of the marginal edges of the ply material about the beads is at present usually performed in a progressive manner. That is to say, one portion of a marginal edge of the ply material is folded over the bead and the folding is then continued progressively around the circumference of the band.

The present invention contemplates numerous improvements in both the method and apparatus for manufacturing tires. It is intended to produce tires of improved construction with a minimum of manual operation and manipulation of the material, and more quickly and at lower cost than heretofore. Particularly, the present invention contemplates improvements in the method of and means for stitching together or compacting the successive bands or layers of ply material, and a novel method of and appa-

tus for folding the marginal edge portions of the ply material around the inextensible beads, in which the folding action is simultaneous around the entire periphery of the edge to be folded.

5 Improvements are also contemplated in the method of and means for supporting a bead and applying the bead to ply material carried by the form or drum.

The principal object of the invention is, therefore, to provide a generally improved method of manufacturing pneumatic tires, and an apparatus for carrying out such method which is relatively simple in design and construction and produces tires rapidly and at a reduced cost.

10 15 The invention aims to provide a tire builder which is substantially automatic in operation and which is controlled by adjustable devices which permit alteration in the timing and sequence of the various operations and movements as desired.

20 Other objects and advantages residing in certain features of construction and combinations of parts will become apparent from the following detailed description of an apparatus embodying the invention, made in connection with the accompanying drawings, in which:

Fig. 32 is a fragmentary detail partly in section showing the stitcher weights and their guides;

Fig. 33 is a horizontal detail showing one of the clutches and taken substantially on the line 33—33 of Fig. 5, being enlarged with respect thereto;

Fig. 34 is a front elevational view with parts broken away of the clutch mechanism shown in Fig. 33;

Fig. 35 is a sectional detail taken substantially on the line 35—35 of Fig. 34 showing the clutch disengaged;

Fig. 36 is a fragmentary detail similar to Fig. 35 showing the clutch in engaged position;

Fig. 37 is a sectional detail with parts broken away taken substantially on the line indicated at 37—37 of Fig. 4 showing the manner in which the actuating arms for the folders are mounted;

Fig. 38 is a vertical sectional detail showing the latch for the carriage shifting crank;

Fig. 39 is a side elevational view of the servicer in diagrammatic form which supplies materials used in the building of tires in accordance with the method and by means of the apparatus herein disclosed;

Fig. 40 is a wiring diagram showing the electrical connections for controlling the operation of the mechanism; and

Figs. 41 through 53 are diagrammatic sectional views showing successive stages in the building of a pneumatic vehicle tire by the method of the present invention with the apparatus illustrated.

The tire builder of the present invention comprises a base A on which is mounted a main or stationary supporting structure M and a movable supporting structure or carriage C. Between the supporting structures and in the central part of the machine is mounted a collapsible drum or form D. In the following description of the machine, these parts, together with the main drive, are indicated by numerals under 100. Each of the supporting structures M and C has mounted thereon a number of devices for smoothing and pressing rubber ply material R on the drum or form D, setting a bead B against the ply material on the drum, and folding the ply material over the bead. The smoothing, setting, and folding devices carried by the structure C operate over or in relation to the left hand end of the drum D, as viewed in Figs. 1 and 2, while the corresponding devices carried by the structure M operate over or in relation to the right hand end of the drum or form. Bead supporting and pressing devices collectively, referred to as bead holders H, are indicated in the description by numerals in the 100's. Devices movable over only relatively small portions of the drum at the ends thereof for compacting and smoothing the rubber ply material are indicated at S and are identified by reference numerals in the 200's. Folders F are provided for folding marginal edge portions of the rubber and cord ply material around the beads B. These folders are referred to in the description by numerals in the 300's. Primary smoothers or pressers, indicated generally at P, are movable over the major portions of the opposite ends of the drum and in the description are referred to by numerals in the 400's. Stitcher wheels W for applying localized pressure to the tire building machine on the drum D are identified in the description by numerals in the 500's, while numerals in the 600's are used in the description of suitable service or supply equipment E. Con-

70
75

trol means is identified by numerals in the 700's and numerals in the 800's are utilized in the description of the method and sequence of operations.

The construction of the smoothers S, pressers P, folders F, and bead holders H, carried by or mounted on the movable carriage C, is substantially the same as the construction of the corresponding parts carried by or mounted on the main structure M. Therefore, the description of the details of these parts or structures will be made primarily with reference to or in connection with the devices on the fixed structure M, it being understood that the construction and operation of corresponding devices or parts carried by the movable structure C are substantially the same, except as otherwise indicated. Additionally, like parts throughout the several figures have been indicated by the same letters and numerals of reference.

Supporting structure

The base A preferably extends the full length of the machine and comprises front and rear channel section members 1 and 2, respectively, disposed in spaced substantially parallel relation to one another with their webs uppermost and connected at intervals by cross channel members 3. The supporting structures M and C each comprise pedestal members 4 which rest on tracks 5 carried by the front and rear channels 1 and 2. Front and rear angle members 6 and 7 are mounted in spaced parallel relation along opposite sides of the pedestal members 4, being secured thereto by suitable means such as welding. Uprights 8 are secured to the ends of the angle members 6 and 7 adjacent the four corners of each of the pedestals 4 and at their upper ends are secured to horizontal frame members 9 which extend transversely across the width of the machine, and horizontal frame members 10 which extend longitudinally of the machine.

As shown in Fig. 2, the pedestal member 4 of the stationary structure M is rigidly secured to the base A by bolts 11, and the main supporting structure M carries the drum or form D, together with electric or other motor 13 for driving the latter. The pedestal member 4 of the carriage structure C is longitudinally slideable on the tracks 5, being guided and restrained against lateral movement by gibs 12 bolted to the base A. These gibs are preferably L-shaped in cross section and embrace flanges 15 of the pedestal member.

Main drive

Extending through the machine and spaced substantially midway between the front and rear sides of the main supporting structure M is a main drive shaft 16 journaled in a bearing block or worm housing 17 secured to the pedestal member 4 of the supporting structure M. One end of the shaft 16 is connected by means of a flexible coupling 18 to a speed reducing drive indicated generally at 19 which is actuated by main drive motor 14 through a belt 20. Preferably, the speed reducer 19 and motor 14 are secured to an extension 21 of the base A.

A drive shaft 22 is journaled in bearing blocks or worm housings 23 and 24 secured to the pedestal member 4 of the supporting carriage structure C. This shaft is disposed substantially midway between the front and rear sides of the supporting structure C and in axial alignment

with the main drive shaft 16. On the end of the shaft 22 toward the shaft 16 is secured a sleeve 25 provided with a square sectioned socket 26 which slidably receives square sectioned end 27 of the shaft 16. Thus a driving connection is maintained between the shaft 16 and the shaft 22 in all positions of adjustment or movement of the supporting structure C.

In each of the supporting structures M and C, relative short shafts 28, 29 and 30 are mounted in spaced parallel relation for actuating the pressers P, folders F, and smoothers S, respectively. The shafts 28 are each journaled in brackets 31 secured to the pedestal members 4, while brackets 32 and 33, also secured to the pedestal members 4, are provided, respectively, with journals for the shafts 29 and 30.

Between spaced end portions of the journal blocks 17 and 24, worms 36 are secured on the shafts 16 and 22, respectively. Gears 37, freely rotatable on the shafts 29, are meshed with the worms 36 so as to be rotated thereby in synchronous relation. Secured to hub 35 of each of the gears 37 is a notched disc 38 forming one element of a jaw clutch indicated generally at 39, which establishes a driving connection between the gear 37 and the shaft 29. Sprockets 40 and 41 are secured on hub 35 of each of the gears 37 so as to rotate therewith. Chains 42 and 43 are trained over the sprockets 40 and 41, respectively, and are trained over the sprockets 44 and 45 secured on sleeves 46 and 47 freely rotatable on the shafts 28 and 30. On the sleeve 46 is secured a notched disc 48 forming one part of a jaw clutch indicated generally at 49, by means of which a driving connection may be established between the driven sprocket 44 and the shaft 30. Similarly, a notched disc 50 is secured on the sleeve 47 and forms one part of a jaw clutch indicated at 51 by means of which a driving connection may be established between the driven sprocket 45 and the shaft 28.

Clutch construction

Each of the jaw clutches 39, 49 and 51 may be of conventional construction, the specific details forming no part of the present invention. They may each embody the same principles and for purposes of illustration the details of clutch 49 have been shown in Figs. 33 through 36, it being understood that the essentials of construction of the other clutches is substantially the same. Secured on the shaft on which the clutch is to be mounted (in this case the shaft 30) is a clutch member 54 which is disposed in confronting relation to the notched side of the notched disc (in this instance the disc 48). As shown in Fig. 34, the disc 48 may be secured against rotation on the sleeve 46 by means of a key 55, while a key 56 prevents rotation of the clutch member 54 on the shaft 30. A portion of the member 54 is cut away adjacent the periphery to provide a radial recess 57 which slidably receives a clutch dog 58 normally urged toward the disc 48 by means of a helical compression spring 59 which bears against a plate 60 disposed across one end of the recess 57. Under the influence of the spring 59 the element 58 normally projects beyond the face of the clutch member 54 so as to be engaged in one of the notches of the disc 48 to establish a driving connection between the parts of the clutch. One or more cam shaped wedge levers 61 are pivoted at 62 to a plate 63 so that the narrow ends of the levers are normally disposed in the

path of the clutch dog 58 as the latter is rotated with the disc 48. Certain of the wedge levers to which specific reference is to be made are identified by lower case letters following the numeral 61, as will hereinafter appear in connection with the description of the other drive clutches. When the clutch dog 58 is engaged by sloping or wedge shaped surface 67 of one of the levers 61, the clutch dog is forced to the right, as viewed in Fig. 35, withdrawing the clutch dog from the notch in the disc 48 with which it was in driving engagement, thus disconnecting the clutch so that the clutch member 54 may remain stationary while the disc 48 may continue to rotate under the influence of the chain 42. Preferably, a shoulder 64 is provided to positively engage the clutch dog 58 and positively arrest the rotational movement of the clutch member 54 in a predetermined position when one of the wedge levers 61 is pivoted inwardly from its outer or inoperative position shown in Fig. 36 to its inner or operative position shown in Fig. 35. In Fig. 34 the limits of movement of the lever 61 are indicated by the broken lines which show the lever in inoperative position and the full lines which show the lever in clutch disengaging position. If desired, a spring pressed shock absorber 65 may be provided in the clutch dog 58 to cushion the impact between the dog and the wedge lever 61.

The plate members 63 are disposed in upright position adjacent the clutches and at their lower ends are bifurcated to provide legs which straddle the clutch shafts. The leg portions of the plates are secured to the journal brackets 30 through 32 at the rear side of the machine and at the upper end of each plate is a horizontally disposed bracket portion 66 which supports the clutch actuating solenoids to be later described.

Forming drum

The drum D is of the collapsible type and is mounted on one end of a shaft 69 and a sleeve 70 disposed about the shaft. The shaft 69 is journaled within the sleeve 70 by means of bushings 71 and the assembly is rotatably journaled or supported in a member or standards 68 secured to the cross members 9 of the supporting structure M. As shown in Fig. 5, the shaft 69 extends beyond the end of the sleeve 70 is journaled in a member or standard 72 carried by an extension portion of the supporting structure. A gear 73, secured on the projecting end of the shafts 69, meshes with a gear 74 (Figs. 2 and 6) journaled on a short shaft 75 journaled in brackets mounted on a platform 76 carried by the supporting structure M. The shaft 75 has secured thereon a pulley which is driven by a belt or belts 77 trained over a pulley on the shaft of the motor 13. This motor is adapted to rotate at different speeds so that the drum D can, if desired, be driven at one speed for applying a band of ply material therearound and at another and faster speed for stitching the plies or tread stock and plies together, as will later appear. During normal operation the rotation of the drum supporting shaft 69 causes synchronous rotation of the sleeve 70, in accordance with standard practice, through the mechanism of the collapsible drum (see Fig. 8). In order to collapse the drum, for the removal therefrom of a completed tire, the rotation of the sleeve 70 is arrested. For this purpose a brake band 78 is provided which frictionally engages a brake wheel 79 secured on one end of the sleeve 70. Actuation of the brake

band 78 is by means of an electromagnet or solenoid 80 secured to a bracket on the platform 76. Armature 81 of the solenoid is link connected to a bell crank lever 82 pivoted at 83 on a bracket supported by the platform 76. The brake band 78 is so attached to the lever 82 that upward movement of the solenoid armature 81, as viewed in Fig. 6, effected by energization of the solenoid, tightens the brake band around the wheel 79 to increase the frictional engagement between the band and wheel, thus stopping the sleeve 70 and effecting collapse of the drum D.

Carriage shifting

Shifting of the carriage C is effected by means of a pair of cranks 84 secured on the ends of a cross shaft 85 journaled in brackets 86 secured to the pedestal member 4 of the movable structure or carriage C. The ends of the cranks 84 are pivotally connected to long pitmans or connecting rods 87 which are pivotally attached to threaded adjusting rods or screws 88. These rods are threadedly received in threaded sleeves 89 rotatably mounted in brackets 90 secured to the channel members 1 and 2 of the base A. The sleeves 89, each of which thus supports one of the pitmans 87 at opposite sides of the machine, are provided with sprockets 91 over which is trained a chain 92. Thus by means of a hand crank 93 secured on an extension portion of one of the sleeves 89, both sleeves may be synchronously rotated to adjust the relative positions of the pitmans 87 with respect to the base A of the tire builder.

The shaft 85 has a gear rotatably mounted thereon and it meshes with a worm 94 secured on the shaft 22 between end portions of the journal block 23. The gear on the shaft 85 is similar to the gears 37 on the shafts 29 and forms the corresponding part of a clutch structure 95 by means of which the shaft 85 may be intermittently actuated as desired. This clutch structure includes two of the cam shaped wedge levers previously described, indicated at 61a and 61b. These wedge levers are interconnected by means of a linkage indicated generally at 96, and are synchronously actuated by an electromagnet or solenoid 97. The cam or wedge levers 61a and 61b of the clutch 95 are adjusted so that the cranks 84 are arrested thereby in positions 180° apart; such, for example, as the position shown in Fig. 3 in which the carriage is at the limit of its movement to the right as viewed from the operator's position at the front of the machine, and the position shown in Fig. 1 in which the carriage or supporting structure C is at its limit of movement to the left, being withdrawn from the drum D to permit the removal of a completed tire.

Preferably, pivoted latches or props 98 are arranged to support the cranks 84 and pitmans 87 in the position shown in Fig. 3 with the movable structure C at its limit of movement to the right in tire building position. As shown in Fig. 38, the props 98 are held in upright position against the ends of the cranks 84 by means of helical tension springs 99. During the movement of the cranks 84 in a clockwise direction, as indicated by the arrow, the props or latches 98 are displaced to the broken line position shown, after which they follow the crank until the latter reaches its limit of movement shown by the full lines, and in this position the latch levers or props lock the cranks against reverse rotation to prevent displacement

or shifting of the supporting structure C during the tire building operation.

Bead setting

The bead setters or holders H are axially aligned with the drum D and each comprises a cylindrical drum 100 having at one end thereof a radially extending flange portion 101 formed at its periphery with a rim 102 to which are attached a multiplicity of axially directed, resilient, spring-like fingers 103. The drum 100 of the bead holder carried by the main supporting structure M is rotatably mounted on the sleeve 70, previously described in connection with the tire building drum or form D. The corresponding drum 100 for the bead setter carried by the shiftable structure or carriage C is mounted for axial movement on a supporting shaft 104 supported by a standard or member 105, which corresponds to the journal member or standard 68 previously mentioned in connection with the drum supporting sleeve 70, and a bracket member 106 mounted on one of the cross members 9 of the supporting structure C and corresponding to the journal bracket or member 72 previously mentioned. Preferably, the shaft 104 is provided at one end with a cylindrical recess 107 which removably receives a spindle portion 108 formed on one end of the drum shaft 69. Thus, the shafts 104 and 69 by interfitting engagement with one another are maintained in axial alignment and mutually support one another when the carriage C is in tire building position.

Slidably mounted on each of the cylindrical drums 100 for axial movement relative thereto is a collar 109 provided with a radially extending flange 110 disposed in spaced parallel relation to the flange portion 101 of the cylinder 100. A presser member 111 is disposed concentrically about the rim 102 of the bead supporting structure. This presser member is of cylindrical form, or substantially so, and is arranged in overlying relation to the spring fingers 103. Radially directed inwardly extending leg portions 112 formed at equally spaced intervals about the circumference of the presser member 111 are disposed in the space between the flange 101 of the bead supporting structure and the flange 110 of the sleeve 109. Helical compression springs 115 are disposed in spaced parallel relation to one another around each drum 100 and are carried by tubular sockets 116 secured to the drum flanges 110. One end of each of these springs, which projects from the socket 116, bears against one of the legs 112. These springs are disposed so as to normally urge the pressure members 111 toward the drum D and against the flange portion 101 of each of the bead holders H. A spider element or ring 117 is rotatably mounted on each of the drums 100 and is disposed against the flange portion 101 thereof. Preferably, a pin 118, secured in the spider 117, rides in a circumferential groove 119 formed in the drum 100, thus preventing axial or longitudinal movement of the spider relative to the drum while permitting limited rotation or circumferential movement of the spider about the drum. One purpose of the spider 117 is to regulate the position of the presser member 111 relative to the bead holding fingers.

The resilient fingers 103 are preferably recessed into the peripheral surface of the rim 102, and may be held in dovetail slots, as shown 75

in Fig. 21. These fingers are separated from one another by narrow bands 120 in the rim 102, which provide spaces 114 (Fig. 9) between the fingers to permit radial deflection thereof. These fingers are preferably constructed of suitable resilient spring material such as steel or brass and are supported in cantilever fashion by the rim 102 so as to project therefrom in the direction of the drum D. The ends of the fingers are bent or curved radially outward as indicated at 121 and then radially inward as indicated at 122, there being a short portion 123 of each finger which is approximately parallel to the axis of the drum supporting shaft 69. The curved or angularly disposed portions 121 and 122 of the fingers are utilized in the folding of the ply material, as will be herein-after described, while the axial portions 123 serve to support the bead as the latter is being pressed against the ply material on the drum D.

As shown in Fig. 24, the presser member 111 is of such axial length that circumferential pressure face 124 thereof is in approximately radial alignment with tip ends 125 of the fingers 103 when the legs 112 of the presser member are disposed flatwise against the flange 101. Upon circumferential shifting movement of the spider 117 about the drum 100 to substantially the position shown in Figs. 18, 19 and 20, leg portions 126 of the spider are forced between the flange 101 of the bead support and the legs 112 of the presser member so as to move or shift the presser axially on the bead support and to cause the ends of the fingers 103 to project beyond the face 124 of the presser member a sufficient distance to expose the bead supporting portions 123 of the fingers. Preferably, the leading edges of the legs 126 are beveled as indicated at 127 of Fig. 20, while corners 128 of the presser member legs are rounded to facilitate the forcing of the spider between the presser member and bead support.

A number of axially directed extensions 129 are formed on the hub portion of the spider ring 117 and are receivable in recesses 130 formed in the end edge of the sleeve 109. These cut-away portions or recesses 130 are of sufficient circumferential extent to permit therein rotative movement of the spider 117 from the position shown in Fig. 24 to the position shown in Fig. 20 in which the spider separates the presser member and bead support. When the sleeve 109 is in retracted position as shown in Fig. 8, the spider 117 may be circumferentially shifted on the drum 100 a sufficient distance to move the extensions 129 beyond the recesses 130. Subsequent movement of the sleeve 109 to the left as viewed in Fig. 25, or toward the bead support, causes similar movement of the drum 100 and fingers 103, the extensions 129 of the spider 117 being interposed between the sleeve and the flange 101 for a purpose to be later described.

The shifting movements of the spiders 117 on the drums 100 is effected by means of a rotatable rod 131 which is journaled at one end in a boss 132 formed on the flange 101 of the bead support and at the other end in a journal block 133 secured to a cross member 134 (Fig. 10) supported by the intermediate members 10 of the supporting structure. A spur gear 135 secured on the rod 131 meshes with a series of racked teeth 136 formed on the periphery of the spider ring 117, so that rotation of the rod 131 effects a circumferential shifting of the spider about the

cylindrical drum 100 in the manner previously described. The journal block 133 is centrally apertured or cut away to provide a recess 137 which confines a pinion 138 against axial shifting movement. This pinion is longitudinally slideable on the rod 131 and has a driving connection with the rod by means of key 139 longitudinally slideable in keyway 140, while permitting longitudinal movement of the rod during movement of the bead setter or holder H toward and away from the drum D. A rack 142 is guided by the journal block 133 and meshes with the pinion 138 to rotate the latter. This rack is reciprocated vertically by means of a cam follower 144 secured on the end of the rack and received in an annular cam track 143 which guides and actuates the follower. The cam track is formed in one face of a gear wheel 145 mounted on a short shaft 146 journaled in extension brackets 147 attached to the brackets 32 which support the shafts 30 previously mentioned. Gears 148 secured on the sleeves 46 mesh with the gears 145 so as to drive the latter from the shaft 16 in timed relation with the other parts of the mechanism. The shape of the cam grooves 143 is such as to interpose the spiders 117 between the bead support flange 101 and the legs 112 of the bead presser, or between the bead support flange and the collar 109, as desired, to enable the apparatus to carry out the tire building operation to be hereinafter described.

Movement of the bead holding and setting device H toward and away from the drum D is effected by means of a pair of rods 151 and 152 which are threaded into sockets formed in peripheral portions of the flange 110 of the collar 109, as indicated at 153. These rods are disposed in spaced apart substantially parallel relation to one another and extend horizontally away from the drum D, preferably being guided by the standards 68 and 105. A stationary guide or slide bar 154 is disposed above and in parallel relation to each of the rods 151 and 152. These slide bars are each supported at one end by one of the bracket members 68 or 105 and at its opposite end by a bracket 155 mounted on upper frame members of one of the supporting structures. The ends of the rods 151 and 152 opposite the threaded connections 153 are secured by adjustable length devices 156 to slides 157 mounted for reciprocation on the bars 154. Associated with each of the slides 157 is a pair of toggle links 158 and 159 which are pivoted together at 165. The links 158 and 159 extend upwardly from their common pivot in diverging relation to one another, the link 158 being pivotally connected to the slide 157 and the link 159 being pivotally connected to an adjustable block 161 mounted on the slide bar. Attached to the pivots 165 are links 162 which extend downwardly therefrom and have their lower ends pivotally connected at 163 to cranks 164 secured on the shafts 30. Upon rotation of the shafts the cranks 164 on the ends thereof move simultaneously so as to actuate the slides 151 back and forth on the bars 154 in synchronous relation with one another, thus moving the bead holders or setters H back and forth on the sleeve 70 and shaft 104 toward and away from the drum D.

As previously mentioned, the shafts 30 are arranged to be driven from the main drive shaft 16 and the drive shaft 22 in timed relation with the operating cycle of the machine by means of the chains 42 and through the clutches 49. These clutches each have a single wedge lever 61c con-

nected by a link 167 to armature 166 of an actuating electromagnet or solenoid 160. Thus the driving connection through the clutch can be arrested at only a single position of the cranks 164, this position being such that the bead holders H are withdrawn from the drum D, and in substantially the positions illustrated in Fig. 8, when the drive is disestablished. The positions of the bead holders at their limits of movement can be adjusted by means of the blocks 161 or the adjustable length connectors 156 so that the correct degree of positive pressure will be exerted against the beads in setting the same against the ply material on the drum D, in the manner to be hereinafter described.

Shoulder smoothers

The shoulder smoothers S, Figs. 8 and 18, each comprise a helical coil spring 200 which is of annular form and is normally disposed about the cylindrical pressure member 111 of the bead setter adjacent the pressure face 124 thereof. A multiplicity of retaining arms 201 hold and actuate the smoother springs 200. These arms are disposed in approximately parallel relation to one another at uniformly spaced intervals around the periphery of the presser 111. Each arm is pivoted at 202 to a clevis bracket 203 secured to the periphery of the flange 110. From the pivots 202 the arms 201 extend toward the drum D over the presser 111, the ends of the arms terminating in removable curved fingers 204 which grasp the spring 200.

The arms 201 are of sufficient length so that when a bead B supported by the fingers 103 is forced by one of the pressers 111 against a band of ply material R on the drum D, as shown in Fig. 18, continued movement of the sleeve 109 toward the drum D forces the smoother spring 200 over the bead B and over rounded shoulder 205 of the drum D. The annular bead presser 111 is of smaller diameter than the tire supporting surface of the drum D, so that in moving onto the drum from the presser, the spring 200 is distended. Furthermore, the spring 200 is normally under tension around the presser 111 so that all portions of ply material on the drum D over which the spring 200 passes are subjected to considerable radial pressure. This pressure is equal around the entire periphery of the drum D so that the ply material (and bead flipper to be later described) are uniformly and evenly compacted by the spring or smoother. If desired, the peripheral outwardly directed edge portion of the presser 111 adjacent the face 124 thereof is curved radially outward as indicated at 206. This curved surface 206 is in circumferential engagement with the spring 200 to prevent the latter moving off the end of the presser 111 except when the presser is positively arrested in its forward movement by the drum D. When the sleeves 109 are retracted to withdraw the smoother springs 200 from the drum D, they slide over the cylindrical drum 100, the latter being urged in the opposite direction to hold the pressers 111 against the beads B by the compression springs 115. At the ends of the cylinders 100, opposite the flanges 101, retaining rings 207 engage the sleeve 109 to limit movement of the sleeves relative to the drums 100. The length of the drums 100 relative to the length of the arms 201 is adjusted so that when the sleeves 109 are engaged by the retaining rings 207, the springs 200 are received on the presser member 111 adjacent the curved edge 206 of the latter.

Folders

Adjacent opposite ends of the drum D, the folders F are mounted on the sleeve 70 and the supporting shaft 104. These folders are disposed in confronting coaxial relation to one another and are of substantially the same construction. For purposes of illustration the construction and operation of the folder mounted on the sleeve 70 is shown in Figs. 11 through 17. Each folder comprises a circular disc-like body member 300 which is provided with an axially offset hub 301 slidable on the sleeve 70 or shaft 104 as the case may be. The outside diameter of each of the discs 300 is slightly less than the inside diameter of circular openings 302 in the ends of the drum D, so that each folder, which is mounted for axial movement relative to the drum, may be moved inside the latter as illustrated in Fig. 8. Desirably, the drum D is provided at its shoulders 205 with interned circumferentially extending radially directed flanges 303 which define the circular openings 302.

A plurality of radially extending dovetail grooves 304 (Fig. 15) are formed in the body 300 to slidably receive folding members 305 which are formed at their outer ends with segmental circumferentially extending folding elements 306. Each of the folders 305 is connected by a link 307 to a collar 308 slidable on the sleeve 70. As shown in Figs. 11 and 14, the body 300 is recessed at 309 to receive the collar 308. Portions of adjacent ends of the folding elements 306 are removed or cut away as indicated at 310 to receive bridging or spanning elements 311 which overlap the ends of the elements 306 and move radially with the folders 305 during the folding operation to be later described. The elements 311 may be retained by bolts 314 secured in the ends of the folding elements 306 and extending through circumferentially elongated slots 315 formed in the elements 311. Axial movement of the collar 308 relative to the folder body 301 effects simultaneous radial expansion or movement of the folders 305 around the entire periphery of the folder F, thus causing the diameter of the folder to increase or decrease as desired.

The axial movement of each of the folders F relative to the drum D is controlled by a pair of rods 316 and 317 (Fig. 10), the ends of which are threaded into the body of the folder as indicated at 318. These rods are disposed in spaced and parallel relation and extend away from the drum D horizontally. Suitable apertures 319 are provided in the flanges 101 of the bead holder drums to accommodate the rods 316 and 317 and the latter are guided at 320 in the standards 68 and 105. The ends of the rods opposite the folders 300 are connected by adjustable length connectors 321 to pivoted arms 322 and 323. These arms are secured against rotation on a pivoted shaft 324 (Fig. 37) journaled in bracket extensions 325 mounted on the brackets 32 which support the shaft 29 previously mentioned. The arm 323 has an extension 326 provided with a roller 327 which rides on a cam 328 secured on the shaft 29 for rotation therewith. The faces of the cams 328 of the two folders are formed so that the back and forth or folding movements of the folder F on the sleeve 70 and the folder F on the shaft 104 are synchronized and follow predetermined courses so as to simultaneously perform the folding operations to be hereinafter described.

Movement of each of the collars 308 is con-

trolled by a pair of rods 331 and 332 which are threaded into diametrically spaced portions of the collar at 333 and extend horizontally away from the drum D in parallel relation to one another and to the rods 316 and 317. Suitable apertures 334 are provided in each of the folder bodies 300 and cylindrical drums 100 to permit free longitudinal movement of the rods 331 and 332 and the latter are guided in the standards 38 and 105 as indicated at 335. The ends of the rods 331 and 332 opposite the collars 308 are pivotally attached by means of adjustable length connectors 336 to the upper ends of pivot arms 337 and 338 (Fig. 37) which are pivotally mounted on the pivot shaft 324 previously mentioned. Desirably, the arms 337 and 338 have an integral hub 342 which embraces the shaft 324 and extends between and spaces the hubs of the pivot arms 322 and 323. An extension arm 339 secured on the hub 342 has a roller 340 which rides on the periphery of a cam 341 secured on the shaft 29 for rotation synchronously with the cam 328. As previously mentioned, the shafts 29 in the two supporting structures C and M are synchronized so that the movements of the cams 328 and 341 carried by these shafts are likewise synchronized and the folding operations or movements performed by each of the folders F are carried out synchronously and simultaneously on the opposite ends of the drum D.

Helical tension springs 344 are connected to the upper ends of the arms 322 and 323 and tensioned in the direction of the drum D, being anchored or secured to one of the cross members of the supporting structure, such as the standards 68 and 105. Similarly, the upper ends of the arms 337 and 338 are provided with tension springs 345 which extend toward the drum D and may be anchored to suitable cross members, such as the standards indicated. The springs 344 and 345 serve to resiliently urge the cam rollers 327 and 340 against the cams 328 and 341 during the sequence of the respective movements of the folder bodies 300 and collars 308.

In Fig. 17 is diagrammatically shown a suitable path which the folding elements 306 may be made to describe under the influence of the cams 328 and 341. In this figure the approximate path of an axially directed lip 347 formed on the folding elements 306 and the bridge elements 311 is indicated by broken line 348. Successive positions of the folding elements are indicated by the broken line figures and the sequence of the positions are shown by numerals. The lips 347 are provided on both the folding elements 306 and bridge elements 311 so as to extend substantially around the entire periphery of each of the folders F. These lips protrude in the direction of the drum D and are effective in folding the fabric or ply material R around the beads B, as will later appear.

The drive for actuating the shafts 29 which carry the cams 328 and 341 is by means of the clutches 39 previously mentioned. These clutches each have three of the wedge levers previously described in connection with Figs. 33 through 36. These levers are indicated in Fig. 5 at 61d, 61e and 61f, and are each pivoted by one of the pins 62 to the supporting plate 63 which straddles the shaft 29. A linkage 349 connects the levers so that they are all actuated simultaneously by armature 350 of electromagnet or solenoid 351 which is connected to the lever 61f by a link 352. The electromagnets or solenoids 351 are supported above the shafts 29 on the bracket portions 66

of the plates 63. By means of springs (not shown) or through the action of gravity, the wedge levers 61d, 61e and 61f are normally disposed and positioned to engage the dogs 58 of the clutches 39 so as to arrest the driving connection between the discs 38 and the shafts 29. When one of the wedge levers 61d engages the dog of one of the clutches 39, the associated shaft 29 stops with the cams 328 and 341 approximately in the position illustrated in Fig. 12. In this position the levers 322, 323, 337, and 338 are in their extreme limit of movement toward the drum D, so that the folders F are disposed within the drum D between the planes of the flanges 303. Upon energization of the solenoids 351 the wedge levers 61d are withdrawn from between the notched discs of the clutches and the clutch dogs 58, so that the drive between the shafts 29 and gears 37 is reestablished to move the cams 328 and 341 in a counterclockwise direction as viewed in Fig. 12 until the driving connection is interrupted by the wedge levers 61e, which engage the cam dogs to withdraw the same from the notched discs of the clutches and stop the drive of the shafts 29. During this movement the cams 328 and 341 rotate approximately 180° and actuate the control arms and rods for the folders F so that the latter describe the path 348 indicated in Fig. 17.

Upon actuation of the solenoids or electromagnets 351 to withdraw the wedge levers 61e from between the respective clutch discs and clutch dogs, the drive for the shafts 29 is re-established and the cams 328 and 341 are rotated to withdraw the folders F from the drum D. During this movement the cams rotate through approximately 90° until the clutch dogs are disengaged from the clutch discs by the wedge levers 61f to arrest the drive of the shafts 29. When the folders have been thus withdrawn from the drum, the latter may be collapsed to remove a completed tire therefrom, as will later appear. Actuation of the electromagnets 351 to withdraw the wedge levers 61f from in front of the clutch dogs reestablishes the drive for the shafts 29, which then rotate the cams 328 and 341 to move the folders F within the drum D. This movement takes about 90° rotation of the shafts and continues until the clutches are disconnected by engagement of the wedge levers 61d by the clutch dogs.

Primary pressers

The smoothers or pressers P for compacting rubber ply material R and tread stock T on the drum D and also for interning the edges of the ply material over the shoulders 205 of the drum, comprise helical springs 400 in the form of annuluses which are supported by arms 401 pivoted intermediate their ends at 402 in bracket extensions 403 of rings 404. The spring pressers 400 are disposed in parallel relation to one another for simultaneous movement in opposite directions over the two ends of the drum D. These pressers may be mounted, when not operating over the drum, around the arms 201 which support the smoothing springs 200, and in concentric relation to the axis of the drum or form D. Each of the rings 404 is supported by a pair of spaced substantially parallel rack bars 405 and 406 (Fig. 10) which are guided at 407 in extension brackets 408 on the standards 68 and 105. Additional guides 409 are provided for the bars 405 and 406 in the upper ends of brackets 410

supported by intermediate frame members 10 of the supporting structures.

Each set of the arms 401 is disposed in spaced parallel relation to one another approximately equi-distant from the axis of the drum D. The ends of the arms toward the drum are provided with removable fingers 411 which grasp the springs 400. The fingers 411 as well as the fingers 204 previously mentioned, are arranged so that in cooperation with the arms or levers to which they are attached, the springs to be held thereby are grasped around more than half their circumference so as to retain their hold thereon while permitting the inner portions of the springs to be free and unobstructed for movement over the drum D or the ply material R or tread stock T, disposed thereabout. Preferably, the springs 200 and 400 are loosely held by the fingers 204 and 411, respectively, so that the springs may roll over the ply material or tread stock while tightly but resiliently embracing the same. The inside diameter across the spring annulus 400 is normally less than the outside diameter of the drum D so that the spring is effective to compact and smooth the ply or other material disposed about the drum when the spring is moving axially over the drum without being held in distended position by the arms 401.

Conical shells 414 each having a relatively short cylindrical portion 415 at its small diameter end, are secured by members 416 to the standards 68 and 105. The shells, thus spaced, have their wide or open ends directed toward one another and the drum D and are approximately coaxial therewith. Rollers 417 journaled in the ends of the arms 401 opposite the fingers 411 which grasp the springs 400 are engageable with the conical surfaces of the shells 414 so as to pivot the arms or levers 401 on the rings 404 as the rings are moved toward or away from the drum D while the shells 414 remain stationary. When the rings 404 are at their limit of movement away from the drum D (see Fig. 10) the rollers 417 are received on the inner surface of the cylindrical portion 415 of the shell to retain the springs 400 in distended position.

In order that the springs 400 may be held in distended position when the rings 404 are moving toward the drum D, latches 418 are secured to the arms 401 and are arranged to be engaged by movable latch rings 419 slidable on cylindrical surfaces 420 of the rings 404. These latch rings are normally urged in the direction of the latches 418 for engagement therewith by a multiplicity of helical compression springs 421 disposed about bolts 422 slidable through apertures in the rings 404 and threaded into the latch rings 419. Preferably, portions of the rings 404 and 419 are removed from about the bolts 422 as indicated at 423 to accommodate the springs 421 when the latch rings 419 are withdrawn from latching position as shown in Fig. 28.

The rings 404 are actuated for movement toward and away from the drum D by the short shafts 28 which have secured on their ends, cranks 424 (Fig. 4). These cranks are pivotally connected to the bottom ends of vertically reciprocable racks 425 guided by plate members 426 pivoted on shafts 427 journaled in brackets 428 secured to the longitudinal frame members 10 of the supporting structures. Secured on the shafts 427 for rotation therewith are gears 429 (Fig. 4) which mesh with the racks 425 to be driven thereby. Desirably, rollers 430 mounted

between the plate members 426 engage the rear sides of the racks 425 to reduce the friction. Also mounted on the shafts 427 are gears 431 which mesh with rack teeth 432 on the underside of the rack bars 405 and 406. During rotation of the shafts 28 the racks 425 oscillate about the shafts 427, causing a similar oscillation of the plate members or sheaths 426 as indicated by the broken and solid lines of Fig. 4.

When the racks 425 are drawn downwardly by the cranks 424 on the shafts 28, the supporting rack bars 405 and 406 are driven so as to move the rings 404 toward the drum D, carrying the pressing springs 400 into juxtaposition over the central portion of the drum (see Fig. 26). Movement of the rack bars 425 upwardly rotates the gears 429 and 431 in reverse direction to retract the rack bars 405 and 406 and withdraw the rings 404 and springs 400 from the drum D to substantially the position illustrated in Fig. 10. At the limit of movement of the rings 404 toward and over the drum D, the latch rings 419 are withdrawn from engagement with the latches 418 so as to release the arms 401, permitting the springs 400 to contract and embrace the material on the drum D, as shown in Fig. 26. This releasing movement of the latch rings 419 is effected by means of a plurality of rods 435 which are threaded into the latch ring at 436 and extend through suitable guide holes 437 in the ring 404. The rods 435 pass through apertures 438 in the shell 414 and through apertures in stop bosses 439 secured to the shell 414. When the rings 404 are moved to the position shown in Fig. 26, the rods 435 slide in the stop bosses 439 until the latter are engaged by collars 440 secured on the rods 435, at which time the movement of the latch rings 419 is arrested. Continued movement of the rings 404 withdraws the latch rings 409 from engagement with the latches 418 to release the arms 401 which permit contraction of the springs 400 about the drum or form D. During reverse movement of the rings 404 the rods 435 slide in the stop bosses 439 and the springs 421 return the rings 409 to latching position.

The shafts 28 are driven from the sleeves 41 mounted thereon through the clutches 51, previously mentioned. Each of these clutches has one of the wedge levers, indicated at 61g, which is normally maintained in position by gravity or otherwise to engage the dog 58 and withdraw the latter from the notched disc 50 so as to disconnect the driving connection between the shaft and the sleeve. The wedge levers 61g of the clutches 51 are connected by links 441 to armatures 442 of electromagnets or solenoids 443 which are supported by the horizontal bracket portions 66 of the plates 63 which straddle the shafts 28. Upon energization of the solenoids 443, as will be hereinafter described, the armatures 442 thereof are drawn upwardly to withdraw the wedge levers 61g from between the dogs 58 and notched discs 50 of the clutches 51, thus permitting the dogs to become engaged in one of the notches of the discs to establish connection between the sleeves 41 and shafts 28. As in the case of the other clutches, release of the armatures of the actuating solenoids after a driving connection has been established in the clutches is ineffective to interrupt or disconnect the clutches until the discs thereof have rotated the dogs 58 into engagement with the inclined surfaces of the wedge levers 61g. Accordingly, each of the clutches 51, which has but a single wedge lever 61g, makes a complete revolution each time

the actuating solenoid 443 therefor, is energized to momentarily withdraw the wedge lever 61g from between the dog 58 and the notched disc 50. Therefore, the cycle of the primary pressers

5 P for each actuation of the clutches 51, includes a forward movement during which the annular presser springs 400 are carried to the center of the drum D and then released to embrace the latter, and a reverse movement in which the springs 400 are drawn apart, toward and over the shoulders 205 of the drum, and retracted into the shells 414 which reset the latches 418 on the latch rings 419 preparatory to the next cycle.

Stitchers

15 Beneath the drum D a pair of stitcher discs or wheels W having threaded hubs 502 are mounted on shaft 503 which is oppositely threaded from the center toward the ends. The threads on the shaft 503 are arranged so that when the stitcher discs or wheels are rotated thereon in one direction, clockwise as viewed in Fig. 30, they are drawn evenly together; while rotation of the stitcher discs in the reverse direction, counterclockwise as viewed in Fig. 30, moves the stitcher discs uniformly apart. The ends of the threaded shaft 503 are supported by arms 504 pivotally mounted on a bar 505 which is disposed in approximately parallel relation to the threaded shaft 503 and has its ends supported by brackets 506 secured to spaced uprights 507. These uprights are mounted on a movable base plate or member 508 which has limited sliding movement in a horizontal plane longitudinally of the machine. As shown in Fig. 9, one side 509 of the plate 508 may be supported on the base A of the machine, being guided by a gib 510 secured to a longitudinally extending angle member 511. The portions of the plate 508 opposite the side 509 may be supported by base member 514 (Fig. 39) disposed at the rear of the machine and at the same level as the member 2 of the base A.

40 The stitcher discs or wheels W are used to apply localized pressure to the material on the drum D which is being formed into a tire. As the drum D is rotated the stitcher discs are raised into engagement with the material on the drum by means of chains 516 connected to the pivoted arms 504 by pins 517 received in one of the plurality of holes 518 through the pivoted arms. The chains 516 extend upwardly from the arms 504 and are guided over sprockets 519 freely rotatable on shaft 520 carried by the uprights 507. A weight 521 is connected to each of the chains 516 so as to draw the stitcher discs or wheels against the material on the drum D with a substantially constant predetermined force. Each of these weights is guided by spaced substantially parallel vertically extending rods 522 and 523, the lower ends of which are carried by a flanged support 524 mounted on the base plate 508. If desired, a stiffening member 525 may be interposed between the flanged member 524 and the base plate to reinforce the latter. The upper ends of each pair of the guide bars 522 and 523 have portions 526 and 527, respectively, of reduced size, which receive and guide a weight 528 which is mounted thereon above the weight 521. The weights 528 are limited in their downward movement by shoulders 529 at the lower ends of the guide rod portions 526 and 527. Passages 530 through the weights 528 are provided for the chains 516 so that the weights 521 may move up and down on the lower portions of the guide rods 522 and 523 independently of

the weights 528. When the weights 521 are elevated by the chains 516 so as to engage the weights 528 and raise the latter off the shoulder 529, the tension in the chains 516 is increased due to the increased weight supported thereby and the localized force applied by the stitcher discs W to the material on the drum D is increased. The position of the shoulder 528 is determined so that the weights 528, in addition to the weights 521, are supported by the chains 516 when the stitcher discs 500 and 501 are separated from the drum D by a relatively thick sectioned layer or layers of tread stock or like material disposed about the drum periphery, while only the weights 521 are supported by the chains 516 when the stitcher discs are separated from the drum by relatively thin sectioned tread stock or like material disposed about the drum periphery. For example, in Fig. 30 broken lines 531 indicate the position of the stitcher discs when the latter are being pressed against the material on the drum D by the weights 521 only, while the broken lines 532 indicate the position of the stitcher discs when the weights 521 engage the weights 528 to raise the latter off the shoulder 529. Accordingly, when the tire building material on the drum D separates the stitcher discs from the periphery of the drum more than indicated by the broken lines 532, both the weights 521 and the weights 528 operate to force the stitcher discs against the material on the drum and apply increased localized pressure thereto.

Local application of pressure to the material on the drum D is commenced at the central portion of the drum and progresses toward the shoulders thereof as the stitcher discs move toward the opposite ends of the threaded shaft 503 because of the rotation imparted to the discs by their frictional engagement with the material on the rotating drum. In order to return the stitchers W to their central position on the threaded shaft 503 shown in Fig. 2, they are lowered into frictional engagement with a driven friction cylinder or rubber roller 533. This roller is mounted in parallel relation to the threaded shaft 503 on a shaft 534 journaled in pedestal brackets 535 supported on the base plate 508. As shown in Fig. 31, the rubber roller 533 is vulcanized to a sleeve 536 which is splined or keyed to the shaft 534 to permit longitudinal sliding movement of the roller on the shaft when the base plate 508 is shifted laterally, as will later appear. The ends of the shaft 534 are journaled in brackets 537 attached to the base A and collars 538, secured on the shaft 534 on opposite sides of the journals resist endwise movement of the shaft.

A flanged sleeve 539 rotatably mounted on the shaft 534 has secured thereon a sprocket 540 driven by a chain 541 trained around a sprocket 542 secured on the main drive shaft 16. A flanged sleeve 543 longitudinally slidably on the shaft 534 while secured against rotation thereon is disposed adjacent the flanged end of the sleeve 539 and one of the two sleeves has secured thereto a friction disc 544 which establishes a driving connection between the sleeves when they are drawn together. Movement of the sleeve 543 into and out of engagement with the sleeve 539 is effected by means of a yoke lever 545 which engages a groove 546 in the sleeve 543. This lever is secured on a pivot rod 547 journaled in the longitudinally extending base member 2 and at the rear of the machine has secured thereon a lever 548 connected by a link 549 to armature

550 of an electromagnet or solenoid 551 mounted on one of the uprights 8 by means of a bracket 552. Normally the solenoid armature 550 is gravitationally or otherwise maintained in lowered position, illustrated in Fig. 31, so as to hold the clutch sleeve 543 disengaged from the clutch sleeve 539. Upon energization of the solenoid, the armature 550 thereof is raised, pivoting the bar or shaft 547 in a counterclockwise direction as viewed in Fig. 31, and moving the sleeve 543 to establish a drive between the rotating sleeve 539 and the shaft 534, which thus rotates the rubber roller 533.

When the stitcher discs or wheels W are lowered into frictional engagement with the roller 533, rotating in a counterclockwise direction as viewed in Fig. 31, the discs are rotated on the threaded shaft 503 so as to move toward one another. At the center of the rubber roller 533 a reduced diameter portion 553 is provided so that the discs W, supported by means of the chains 516, automatically become disengaged from the rubber roller when they reach their central position on the shaft 503.

To lower the stitchers W into engagement with the rubber roller 533, the weights 521 and 528 are raised by lifts 556 which have spindle portions 557 slidable in sockets 558 formed vertically through the bottom of the weights 521. The lifts 556 are each connected by a link 559 to a crank 560 mounted on a short shaft 561 journaled in brackets 562 mounted on the base plate 508. The two shafts 561 for actuating the lifts for the two sets of weights are connected together for synchronous rotation by means of sprockets 563 around which is trained a chain 564. One of the shafts 561 has secured thereon a sprocket 565 driven by a chain 566 trained over a sprocket 567 (Fig. 7) secured on one end of a driven shaft 568. This shaft is disposed in parallel relation to the shafts 28, 29 and 30 across the supporting structure M and is journaled in brackets 569 secured to the pedestal member 4.

A sleeve 570, rotatable on the shaft 568, has secured thereon a sprocket 571 which is driven by means of a chain or belt 572 trained over a sprocket 573 on the sleeve 47, which in turn is driven from the main drive shaft 16 in the manner previously described. A driving connection is established between the sleeve 570 and the shaft 568 by means of a clutch indicated generally at 576 which is constructed similarly to the clutch 49 previously described and includes a notched disc 577 secured to the sleeve 570 and which is arranged to be engaged by the clutch dog 58 to establish a driving connection as previously described. The clutch 576 is provided with two wedge levers 61^h and 61^j which are arranged to interrupt the driving connection between the sleeve 570 and the shaft 568 so as to stop the crank 560 in either its uppermost position, indicated by the solid lines of Fig. 30, or in its lowermost position, indicated by the broken lines of the same figure.

When moving to their uppermost positions the cranks 560 raise the lifts 556 so that shoulders 578 thereof engage the undersides of the weights 521 to raise all of the weights in such manner as to lower the stitchers 501 to rest on the rubber covered roller 533, as shown by the full lines of Fig. 30. When the cranks 560 are in the lowermost position the lifts 556 are lowered so that the shoulders 578 are separated from the weight 521, as shown in Fig. 32, and the spindles 557 are partially withdrawn from the sockets 558. When

thus lowered the weights 521 are supported by the chains 516, as previously mentioned, while the weights 528 are supported by either the shoulders 529 of the guide rods or by the weights 521, depending upon the thickness of the tire building material on the drum D. Both of the wedge levers 61h and 61j are actuated simultaneously by a linkage 579 connected by a link 580 to armature 581 of an electromagnet or solenoid 582 mounted on bracket portion 66 of the supporting plate 63 which straddles the shaft 568. When the solenoid 582 is energized, the wedge levers 61h and 61j are pivoted outwardly so that the clutch dog 58, previously held in withdrawn position by one of the wedge levers, is released to engage the notched disc 577 and establish a driving connection which is maintained for half a revolution of the shaft 568, and until the clutch dog is again engaged by one of the wedge levers 61h or 61j.

Servicer

At the rear of the machine and in line with the drum D is service equipment indicated generally at E. The specific construction of this servicer forms no part of the present invention, but the combination of the servicer with the machine, the unique combination of the servicer and the machine, and the method and means for adjusting the two simultaneously is of considerable importance and forms an important feature of the invention. Referring to Fig. 39, the servicer is shown supported on the base plate 508 for movement therewith and comprises upright frame members 600 and horizontal frame members 601. Mounted on the horizontal frame members 601 for rotation about a vertical axis is a turret 602 which is guided and supported by a vertical spindle 603. This turret carries vertically spaced pairs of rotatable members 604 around which are trained pairs of endless belts 605 carrying feed spools 606 and take-up spools 607.

An operator, in using a machine embodying the present invention for building a tire, draws the rubber impregnated cord or fabric material R from one of the spools 606 over a supporting apron 609 and onto the drum D. As the ply material R is withdrawn from one of the spools 606, a continuous strip of liner material 610 which separates the layers of ply material on the spool 606 is automatically wound up by one of the spools 607. When the ply material or fabric from one of the spools 606 has been exhausted, the operator rotates the members 604 to bring the next adjacent set of feeder and take-up spools 606 and 607, respectively, into position. When all of the spools carried by one set or pair of the endless members 605 have been exhausted the turret 602 is rotated to bring the set of spools carried by another pair of endless members 605 into operative position with respect to the building drum D. While the ply material R is being used from the spools carried by one of the sets of endless members 605, the other set or sets of spools are replenished or loaded with fresh ply material. In this manner the tire building operations on the drum D can be carried out substantially continuously without interruption for the bringing up of new material supplies.

A spool 611 containing a strip of relatively thin broad rubber material known as squeegee stock 614 is supported by the uprights 600 of the servicer. Successive layers of the squeegee stock on the spool 611 are separated from one another

5 by a continuous liner strip 613. In withdrawing the stock from the spool the strip of squeegee material and the liner are carried around a stripping roller 612 and then forwardly and around a movable roller 615 which can be advanced from the full line position shown to the broken line position in which it bears against the periphery of the drum or form D. The squeegee stock and liner are arranged so that the squeegee material is on the outside of the roller 615 and is brought into adhering contact with the ply material on the drum D when the roller 615 is advanced to the broken line position shown. A take-up roller 616 is supported in the framework of the servicer E and is driven in synchronous relation with the drum D. The roller 616 receives the liner material 613 from which the squeegee rubber stock 614 has been stripped by the material on the drum D.

20 A pair of reels, one of which is shown at 617, are rotatably supported in the frame of the servicer E and carry continuous strips of chafer material 618, successive layers of which are separated from one another by continuous strips of liner material 619. The chafer material 618 is supported in a festoon by rotatable guide members or rollers 620 carried by the frame of the servicer, while the liner material 619 is carried around supporting rollers 621 and wound on a take-up reel 622 which is driven in synchronous relation to the drum D under the control of the operator.

25 Above the rollers 616 and 615 for the squeegee stock 614 is a substantially horizontal conveyor comprising a multiplicity of parallel closely spaced rollers 623. This conveyor is adapted to receive and support a strip of tread stock material T which is of sufficient length to form an annular band around the drum D. Each time that the operator of the machine withdraws one 30 of the tread stock strips from the conveyor 623 to place the same around the drum in the building of a tire, an assistant places another tread stock strip on the conveyor in readiness for the next tire built.

35 In order to manufacture tires of different size on the machine of the present invention, provision has been made for altering the effective length of the drum D and for making corresponding adjustments in the relative positions of the smoothers, folders, pressers, and bead holders, as well as the servicer E. As shown in Fig. 8, the drum D may be shortened or lengthened by moving an end portion 627 or 628 relative to body portion 629, there being a thin cylindrical band 630 which spans the gap between the end portions 627 and 628 and is in telescoping relation thereto. When the length of the drum D is altered, the movable supporting structure or carriage C is advanced or retracted by means of the hand crank 93 which rotates the threaded sleeves 89 to advance or retract the threaded rods 88 in the manner previously described. The servicer E is shifted longitudinally of the machine by means of a threaded rod 631 which threadededly engages a nut 632 secured to a member 633 attached to the underside of the base plate 508. The threaded adjusting screw or rod 631 is held against endwise movement by means of a pedestal 634 (Fig. 1) attached to the foundation on which the machine is supported. Rotation of the screw 631 in one direction moves the base plate 508, carrying both the stitchers W and the servicer E to the right, as viewed in Figs. 1 and 2, while rotation of the screw 631 in the op-

posite direction moves both the stitchers and the servicer to the left as viewed in the same figures. In this manner the tire building materials carried by the servicer E are all maintained in alignment with the drum D regardless of the size to which it is adjusted.

Control

The tire builder of the present invention may be driven in any suitable manner, it being contemplated to actuate the component instrumentalities thereof by various means such as hydraulic or mechanical drives. For purposes of illustration the machine has been shown equipped with electrical drive motors 13 and 14, power from the latter being controlled through the clutches described. In order that the tire builder may be used to greatest advantage an automatic control has been uniquely associated with a manual control. Thus, those operations which may be automatically performed can be carried forward with expedition and in proper sequence, while those operations which are to be manually performed can be carried out by the operator in accordance with his optimum speed and efficiency without danger and without the mental hazard of having to keep up with a machine.

For governing the energization of the motors 13 and 14 and the several clutch actuating solenoids, a control diagrammatically illustrated in Fig. 40 may be used. A suitable source of electric current, which may be either direct or alternating current as desired, is supplied through main conductors L1, L2, and L3. In the embodiment illustrated it is assumed that direct current is being employed, it being understood that conventional or well known changes in the specific controls employed may be resorted to for converting the apparatus to alternating current operation or a combination of alternating current and direct current. The sequence of operations is determined by an electrical timing control 700 which is diagrammatically shown in the drawings. Essentially this timing control comprises a multiplicity of circular contact discs or the like which are numbered consecutively from 701 to 727, inclusive. These discs are mounted in coaxial alignment with one another in spaced apart relation on a rotatable control shaft 732 suitably supported and driven at a substantially uniform speed by an electric control motor 733. The shaft 732 is driven by the motor 733 preferably through a suitable speed reducing device (not shown) at a relatively slow rate of speed, so that it makes one revolution for each complete operating cycle of the tire builder.

Motor 733 is energized from conductors L1 and L2 under the control of a relay 734. A manual main starting switch 735, upon being actuated, energizes holding magnet or coil 736 of the relay 734 so as to actuate armature 737 and draw contactor 740 across contacts which connect conductor L2 to a wire 741 connected to the motor 733. The armature 737, when actuated by the holding coil 736, also draws contactor 742 across contacts which maintain the energization of the holding coil through a wire 743 connected to a contact which establishes connection with conductor L1 through one of the contact discs 22 through 25, inclusive, as will later be described. It is to be understood that each of the contactor discs 701 through 727 is arranged to effect an electrical connection between contacts 744 and 745 during only a portion of each revolution of

the contactor with the shaft 732. Each of the disc contactors may be individually rotated or set on the shaft 732 and then locked in place in adjusted position so that the period of time and 5 the portion of the cycle of the shaft 732 during which an electric connection may be established across each of the contactor discs may be regulated and timed as desired. Furthermore, although the contact devices 701 through 727 have 10 been referred to as contactor discs, it is apparent that various other types of switches such as mercury switches under cam control might be employed. Therefore, while contactor discs 722 through 725 are employed to control the holding 15 coil 736 of the relay 734, a single contact switch might be used. In such case the single contact switch would be so operated as to maintain a closed circuit through the holding coil 736 during certain predetermined portions of the cycle 20 of the machine. However, in the embodiment of the invention illustrated a number of contactor discs are shown since it is contemplated that each contactor disc shall be arranged to effect an electrical connection between its contacts 744 and 745 only during a single portion of 25 the cycle of the machine. The length of time during which each of the contactor discs or devices maintains the connection between its contacts 744 and 745 is to be adjusted or determined 30 so as to allow for completion of the particular operation or cycle of operations to be governed thereby. The contact 744 of each of the timing devices 701 through 727 is connected to conductor L1, while the contacts 745 are respectively 35 connected to the various control devices in the manner to be later described.

The actuating motor 14 is connected to conductors L1 and L2 through a conventional starter 746 and remains in continuous operation so 40 long as the starter and main line switch 730 is closed.

The main drive motor 13 for rotating the drum or form D is connected to the source of electric current through a main motor control 45 which includes forward and reverse switches 747 and 748, respectively, and high and low speed switches 749 and 750, respectively. The main motor 13 has field coils 751 and 752, the former being series connected with armature 753 of the 50 motor through the forward and reverse switches, as will later appear, while the coil 752 is connected to the main conductors L1 and L3.

Limit switches 754 and 755 are series connected and interposed in an electrical conductor or wire 55 757 which connects main conductor L2 to one side of each holding coil for the several switches in the main motor control. The limit switches are provided so that the main motor 13 cannot be set in operation while the several instrumentalities or devices of the machine are in position 60 to be damaged thereby. For example, the limit switch 754, Fig. 2, is arranged to be controlled by a mechanism which actuates the bead setter or holder H. This switch is only closed when the bead setter or holder is in retracted position away from the drum D. The limit switch 755 is responsive to the movement of the mechanism which actuates the primary pressers P and is only closed when the pressers are in retracted 65 position away from the drum D.

The contact 745 of the control or contactor disc 701 is connected by a wire 758 to one side of the electromagnet or solenoid 80 which actuates the brake 78—79 on the drum sleeve 70. The 75 contacts 745 of the contactor discs 702 through

704 are connected by wires 759 to one side of holding coil 760 of the main motor forward control switch 747, which coil is arranged to actuate armature 761 of the switch to move or close the contactors 762 and 763. These contactors respectively connect wires 764 and 765 leading to the two sides of the armature 753 of the motor 13 with wires 766 and 767 which in turn, are connected respectively to one side of the field coil 751 of the motor 13 and to contacts in the high and low speed switches 749 and 750 of the main motor control.

A circuit for actuating the main motor 13 is completed through either the high or low speed switches 749, 750 of the main motor control which are responsive to a hand switch 768. This switch has a contactor 769 connected to main conductor L1 and arranged to energize either holding coil 770 of the high speed motor control switch 749 or holding coil 771 of the low speed motor control switch 750 through conductor wires 772 and 773, respectively. Interposed in the conductor wires 772 and 773 are the control discs 721 and 726, respectively, which are arranged to prevent actuation of the main motor 13 for high speed operation except during a predetermined portion of the operating cycle of the machine and also to prevent low speed operation of the main motor 13 except during a certain portion of the machine cycle, as will later appear.

When the forward control switch 747 is closed, as previously described, the main motor 13 may be run at high speed by energizing the holding coil 770 of the switch 749 through the switch 768 and the contactor disc 727. Armature 774 of the high speed switch 749 closes series connected contactors 775 which connect the conductor wires 767 with the main conductor wire L3. In this manner the main motor 13 is energized for high speed forward operation, the field coils 751 and 752 each being connected to the main conductor wire L1.

When rotating in a forward direction the main motor 13 rotates the drum or form D in a clockwise direction, as viewed in Fig. 30, so that the top of the drum moves toward an operator in front of the machine. Movement of the contactor lever 769 of the hand control switch 768 to connect the main conductor L1 with wire 773 energizes the holding coil 771 of the low speed control switch 750 so that armature 776 thereof actuates series connected contactors 777 thereof to connect wire 767 with the main conductor wire L3 through a resistor 778 which impedes the current flow and energizes the main motor 13 for forward operation at reduced speed. As previously mentioned, however, the hand switch 768 is subordinate to the contactor discs 726 and 727 which determine the portions of the operating cycle of the machine during which the high and low speed switches can be closed.

Reverse operation of the main motor 13 is controlled through contactor disc 705 which energizes holding coil 779 of reverse control switch 748 through conductor wire 789, thus actuating armature 780 of the switch to close contactors 781 and 782 which respectively connect the wires 765 and 764 with the wires 766 and 767, previously mentioned, to reversely connect the armature 753 of the main motor with the field coils 751 and 752 thereof.

Contactor discs 706 and 707 have their contacts 745 connected by a conduit or wire 783 to one side of the electromagnet or solenoid 551

which controls the clutch 539—543 for driving the rubber covered roller 533.

Contactor discs 708 through 711 have their contacts 745 connected by a wire or wires 784 to one side of electromagnet or solenoid 582 which controls the clutch 576 for raising and lowering the weights 521 and 528.

The contacts 745 of the contactor discs 712 through 714 are connected by a wire or wires 785 to one side of each of the electromagnets or solenoids 443 which actuate the clutches 51 of the primary pressers P. The contacts 745 of contactor discs 715 and 716 are connected by a wire or wires 786 to one side of the electromagnets or solenoids 160 which control the clutches 49 of the bead holders and setters H and smoothers S. The contacts 745 of the control discs 717 through 719 are connected by a wire or wires 787 to one side of each of the solenoids 351 which control the clutches 39 for governing the actuation of the folders F while the contacts 745 of the control discs 720 and 721 are connected by a wire or wires 788 to the electromagnet or solenoid 97 which controls the clutch 95 through which power is supplied to advance and retract the movable structure or carriage C.

One side of each of the clutch actuating solenoids mentioned above is connected to main conductor wire L2 so that when the respective contactor or control disc therefor effects an electrical connection across its contacts 744 and 745, the solenoid is energized to actuate the particular clutch to which it is connected in the manner described.

If desired, a foot switch 790 may be provided for selectively energizing the drum motor 13 for forward or reverse movement. This foot switch has a movable contactor 791 connected to main conductor wire L1 and arranged to be brought into electrical connection with either the wire 759 or the wire 789 for forward or reverse operation, respectively, of the motor 13.

Operation

In the description of the operation of the machine, it will be assumed that a tire has just been removed from the collapsed drum and the shiftable structure or carriage C is withdrawn or moved to its extreme limit of movement to the left, as viewed in Fig. 1. The main switch 730 is closed so that the actuating motor 14 is energized and in operation, having previously been started through the starter 746. The control motor 733 will have been arrested, as later appears, and all of the operating or tire building instrumentalities of the machine are motionless. The operator then places a bead B on the straight portions 123 of the fingers 103 and against the circular pressure face 124 of each of the bead holders H. Preferably, each of the beads which may be prefabricated according to present practice, has disposed thereabout a layer or layers of rubber coated or impregnated fabric or cord material which is circumferential in extent and extends radially outward from the bead to form a flipper 801.

With the beads in place, the operator closes the manual start switch 735, preferably of the button type, which actuates the relay 734 to energize the motor 733 and set the control shaft 732 in operation. The circuit through the holding coil 736 of the relay 734 is maintained through contactor disc 722 which keeps the motor 733 in operation after the operator releases the start switch 735. Shortly after rotation of the

control shaft 732 is commenced, the contactor discs 4, 17, and 20 make connection between their respective contacts 744 and 745 so as to energize the holding coil 760 of the motor forward control switch, the solenoids 351 of the folding instrumentalities, and the solenoid 97 which controls the carriage shifting clutch. The closing of the motor forward control switch 747 by the contactor disc 704 energizes the motor 13 through the high speed motor control switch 749. It is to be understood that during this period of rotation of the control shaft 732, the control disc 727 is still in that portion of its cycle in which it makes an electrical connection between its contacts 744 and 745 so that the hand control switch 768 can energize the coil 770 of the high speed motor control switch 749 through the wire 772. The control disc 26 is currently in that portion of its cycle in which no electrical connection can be made between its contacts 744 and 745 and the low speed motor control switch 750 cannot be closed. The energization of the folder control solenoids 351 actuates the armatures 350 to momentarily withdraw the wedge levers 61f from between the clutch dogs and notched discs of the clutches 39, so that the shafts 29 are rotated through approximately 90° or a quarter revolution to move the folders F within the drum D through the openings 302 in the ends thereof from approximately the positions illustrated in Fig. 2 to approximately the positions illustrated in Figs. 8, 12, and 41. Meanwhile the electromagnet or solenoid 97 has actuated the armature thereof to momentarily withdraw the wedge lever 61a of the clutch 95 from between the clutch dog and notched disc so as to rotate the shaft 85 for approximately 180° or half a revolution to substantially the position illustrated in Fig. 3 in which the cranks 84 are engaged by the latches 98, Fig. 38, to prevent reverse movement of the cranks. The contactor discs 4, 17 and 20 maintain electrical connections between their contacts for a relatively short period of time, so that the holding coil 760 of the forward motor control switch releases the armature 761 thereof to stop the motor 13 after only sufficient high speed rotation thereof to "throw out" the form or drum D to its cylindrical shape in readiness for the building of a tire thereon. Also the solenoids 351 and 97 are deenergized so that the wedge levers 61d of the clutches 39 withdraw the clutch dogs 58 and arrest the movements of the shafts 29 after a quarter revolution and with the folders F within the drum D, and the wedge lever 61b of the clutch 95 withdraws the clutch dog from the disc to arrest the rotation of the shaft 85 after half a revolution. Shortly after the contactor discs 4, 17 and 20 break the electrical connections between their contacts 744 and 745, the contactor disc 22 breaks the electrical connection between its contacts to deenergize the relay holding coil 736 and stop the control motor 733. Meanwhile, however, the contactor disc 26 has effected an electrical connection between its contacts while the contactor disc 27 has broken the electrical connection between its contacts. The operator then moves the control lever 763 of the hand control so as to make an electrical connection between the power conductor L1 and the wire 773 through the contactor disc 26. Thus the control is set so that by actuation of the foot switch 790, the operator can connect the main motor 13 for either forward or reverse operation at low speed.

In describing the building of a tire by means

of the machine illustrated in the drawings, reference will be made to Figs. 41 through 53 which illustrate in diagrammatic form successive and different steps or stages in the process. These figures show in section the operations performed over one portion of one of the shoulders 205 of the drum, it being understood that the same operations or steps are simultaneously performed or substantially so around the entire circumference of both shoulders of the drum.

From one of the feed spools 606 of the service equipment E the operator draws a strip of rubberized ply material R which preferably consists of a multiplicity of parallel cords coated on one or both sides with rubber and disposed in parallel relation diagonally with respect to the length of the strip. If desired, the rubberized ply material R may be supplied on the spools 606, or otherwise, in composite or laminated form including a bottom layer 802 and a top layer 803, Fig. 41. The individual cords of the layers or plies 802 and 803 are disposed in opposite directions in accordance with conventional practice in building tires of this character. The leading ends of the rubberized cord plies 802 and 803 are pressed against the top surface of the drum or form D and the latter slowly rotated in a forward direction by actuation of the foot switch 790. This rotation of the drum D draws the ply material from the supply spool 606 and wraps the same about the peripheral surface of the drum. After one revolution of the drum the operator releases the foot switch 790 which stops the motor 13 and the drum. He then cuts or otherwise severs the layers 802 and 803 to proper length and makes a suitable connection between the cut end or ends and the leading end or ends thereof which were originally placed against the drum. If desired, the layers 802 and 803, drawn from different spools, may be placed about the drum or form one at a time rather than simultaneously.

After the operator has fastened the ends of the first two layers 802 and 803 of ply material together, he depresses the start button or switch 735 to energize the relay 734 and set the control motor 733 in operation. After release of the start button 735, energization of the relay holding coil 736 is maintained through the contactor disc 123 which now effects electrical connection between its contacts 744 and 745. Shortly after the control shaft 732 starts to move, the contactor disc 112 makes a connection to the solenoids 443 of the clutches 51. The armature 442 of these solenoids momentarily withdraws the wedge levers 61g from between the clutch dogs and the clutch discs to permit a single revolution of each of the shafts 28. As previously mentioned, these shafts actuate the primary pressers P, the annular squeezing springs 400 of which are moved toward one another to positions around the central part of the drum D. Latches 418 are then automatically released by the latch rings 419 so that the springs contract and tightly embrace the layers 802 and 803 of rubber ply material around the entire periphery of the drum. As the rack bars 405 and 406 are retracted by the gears 431, the presser springs 400 roll or otherwise move lengthwise or axially over the drum D away from one another and toward the opposite ends of the drum to press and compact the layers of ply material together, thus smoothing out wrinkles and forcing out entrapped air. As each of the presser springs 400, tightly embracing the drum, moves from approximately the position shown by the full lines of Fig. 41 to approximately the position shown by the

dotted lines of that figure, the layers or plies 802 and 803 of the rubber ply material which project beyond the ends of the drum are folded radially inward over the shoulders 205 to approximately the broken line position indicated. This inturning or folding of the marginal edges of the ply material occurs simultaneously around the entire circumference of the ply material on the drum, so that the action is even and uniform throughout the entire circumference of the marginal edges of the ply material. Thus the inturning of the ply material is effected in such manner as to promote a more even distribution of the individual cords in the rubber material R and the undesirable overlapping or creasing of successive or adjacent portions of the ply material along or about the shoulders of the drum is avoided. As the shafts 28 complete their revolution the wedge levers 61g withdraw the clutch dogs from the clutch discs of the clutches 51 to stop the shafts 28.

As the primary pressers P are being retracted from the drum D after having compacted the layers 802 and 803 of ply material, contactor disc 702 effects energization of the holding coil 760 of the forward motor control switch so as to connect the main motor 13 with the source of electric current and rotate the drum D in a forward direction at low speed, it being understood that the holding coil 771 of the low speed control switch 750 has been maintained closed through the hand control switch 768 and the contactor disc 726. With the drum rotating at slow speed the contactor disc 708 effects an electrical connection across its contacts 744 and 745 so as to energize the electromagnet or solenoid 582 which actuates the armature 581 thereof to momentarily withdraw the wedge lever 61h from between the clutch dog and clutch disc of the clutch 576 and thereby drivingly connect the shaft 568 to the main drive shaft 16. This driving connection is maintained for approximately half a revolution of the shaft 568 or until the lifts 556 have been lowered to substantially the position illustrated in Fig. 32, in which the weights 528 are supported on the shoulders 529 of the guides 522 and 523 and the weights 521 are supported by the chains 516 which have drawn the stitcher wheels or discs W into engagement with the layers or rubberized ply material R on the rotating drum D. The wheels or discs W are rotated by frictional engagement with the ply material on the drum and move progressively apart while applying localized pressure to the ply material on the rotating drum or form. At the shoulders 205 of the drum the wheels move progressively over marginal portions of the ply material layers which previously had been folded inwardly by the primary pressers P. As the wheels or discs W ride over the shoulders of the drum, completing their first stitching operation, the contactor disc 709 effects energization of the electromagnet or solenoid 582 so that the armature 581 of the latter momentarily withdraws the wedge lever 61j from the dog of the clutch 576 and the shaft 568 is rotated approximately 180° or half a revolution until the clutch dog is engaged by the wedge lever 61h which stops the rotation of the shaft 568. This half revolution of the shaft 568 moves the lifts 556 upward by means of the mechanism previously described to approximately the position illustrated in Fig. 30 in which the stitcher discs or wheels W rest by gravity on the rubber covered roller 533. Meanwhile, however, the contactor disc 706 has effected an electrical connection which energizes the sole-

noid or electromagnet 551, shifting the clutch member 543 into engagement with the driven clutch member 539 so that the shaft 534 is rotated thereby. Accordingly, when the wheels W engage the rotating rubber covered roller 533, they are rotated reversely to the direction in which they had been rotated by the drum D so that they move toward one another on the threaded shaft 503. When the wheels W approach one another at the center of the threaded shaft, they ride over the tapered ends of the reduced diameter portion 553 of the rubber coated roller 533 where they are supported by the chains 516 out of engagement with the rubber covered roller. It is to be understood that the contactor disc 706 maintains energization of the solenoid 551 over a sufficient period of time to insure that the wheels W are returned to their central position. As the contactor disc 709 causes energization of the solenoids 582, which effects the lowering of the wheels W from the drum D, the contactor disc 702 interrupts the circuit of the holding coil 760 of the forward motor control switch 747, thus releasing the armature 761 thereof and stopping the motor 13.

After the lowering of the stitcher wheels W and the stopping of the drum D, continued rotation of the control shaft 732 causes the contactor disc 715 to effect an electrical connection which energizes the electromagnets or solenoids 160. The armatures 166 of these solenoids raise the wedge levers 61 of the clutches 49 to effect driving connections between the sleeves 46 and the shafts 30. Energization of the solenoids 160 is maintained by the contactor disc 715 so that the wedge levers 61 do not release the clutches until after two revolutions of the shafts 30, thus effecting two successive and uninterrupted movements of the holders H and smoothers S toward and away from the drum D in the manner now to be described. This rotation of the shafts 30 raises the links 162 which spread the toggle levers 158 and 159, forcing each pair of the rods 151 and 152 toward the drum D so that the beads B carried by the fingers 103 of the holders H are forced by the pressure faces 124 of the pressers 111 against the inturned edge portions of the layers 802 and 803 of the rubber ply material R disposed over the drum flanges (Fig. 42).

In the building of a tire by the machine of the present invention the bead holders H carrying the smoothers S are advanced and retracted a number of times, three in the embodiment illustrated. Each time the bead holders and smoothers are advanced toward the ends of the drum or form D a different operation or step in the tire building process is performed. Accordingly, the relative positions of the several parts of the bead holders and ply smoothers are altered when the devices are retracted by means of the spiders or spacing elements 117. As previously described, the positioning of the spiders 117 between the flanges 101 of the cylindrical drums 100 and the legs 112 of the pressers 111 or the flanges 110 of the collars 109, is controlled by rotatable rods 131 actuated by means of racks 142 which have cam followers 144 in the annular cam tracks 143 of the gears 145. Since the spiders 117 are each to be successively shifted to three different positions during the building of a tire, the gears 145 are arranged to make a single revolution for each tire building cycle of the machine, and the ratio between the gears 145 and the gears 148 on the shafts 30, which drive the gears 145, is 3:1. Thus, for each rotation of

the shafts 30, advancing and retracting the holders H and smoothers S relative to the ends of the drum, the gears 145 with the cam tracks 143 each move through $\frac{1}{3}$ of a revolution.

During the first revolution of the shafts 30, which moves the bead holders H and smoothers S toward the ends of the drum for the purpose of positioning the beads B against the shoulders of the drum as shown in Fig. 42, the cam follower 144 moves over a portion of the cam groove 143 between the lines indicated at 804 and 805. While the cam follower 144 is in the portion of the cam groove 143 between the lines 804 and 805, the legs 127 of the spiders 117 are between the legs 112 of the pressers 111 and the flanges 101 of the drums 100, substantially as shown in Figs. 18, 19 and 20. Thus during the first movement of the bead holders the fingers 103 remain substantially in the position shown in Figs. 42 and 43, in which the straight portions 123 thereof are closely adjacent the pressure faces 124 of the pressers 111. Thus all the fingers of each bead holder form a seat approximately annular in extent which engages the inner circumferential surface of a bead positioned thereon, while the pressure surfaces 124 closely adjacent thereto prevent shifting of the beads on the fingers and serve to force the beads firmly against the ply material on the shoulders of the drum during the bead setting operation and without movement of the beads relative to the holding fingers 103.

When the beads B carried by the bead holders H are pressed against the ply material R on the shoulders 205 of the drum D, as shown in Fig. 42, the movement of the pressers 111 is arrested. The rods 151 and 152 continue, however, to advance the collars 109 toward the tire building form. This action causes the collars 109 to slide on the drums 100 and to compress the springs 115 which exert increased pressure against the pressers 111 and firmly "set" the beads against the ply material on the drum. It is to be understood that the ply material R and the fabric or cord material out of which the flippers 801 are formed is of a sticky or tacky nature, so that upon being pressed together they securely adhere to one another. The continued advancing movement of the collars 109, after arresting of the movement of the pressers 111 in the manner described, forces the annular springs 200 of the smoothers S over the beads B and over the shoulders 205 of the drum onto the cylindrical portion of the latter to substantially the position indicated by the solid lines of Fig. 43. During this movement of the smoothing springs 200, stretching the same, the flippers 801 of the beads are circumferentially pressed or ironed against the first layers of rubber ply material R on the drum D. A particular feature of the present invention is the cooperative action between the pressers 111 of the bead holders and setters and the springs 200 of the smoothers S. It is to be noted that the radial width of the circular pressure faces 124 of the bead pressers 111 is approximately equal to the radial width of the beads B, the outer edges of the latter preferably projecting a slight distance radially beyond the outwardly curved edges 206 of the pressers. Accordingly, as the advancing movement of the smoothers S carries the springs 200 forwardly from their embracing position around the pressers 111, the springs move progressively over the curved edges 206 of the pressers onto the beads B and thence against and over the

flippers 801. This movement of the springs 200 is simultaneous around the entire circumference of the beads, so that the folding of the flipper and the pressing of the same against the ply material R of the drum or form is performed simultaneous about the entire circumference of the bead and flipper.

Another feature of the invention is that while the springs 200 are moving over the ply material and flippers 801 on the drum, the pressers 111 of the bead holders H hold the bead against the shoulders of the drum with increased force and the resilient fingers 103 remain in engagement with the beads around the entire inner circumference of the latter. As previously mentioned, the springs 200 may either slide or roll over the flippers 801, the curved fingers 204 embracing but not gripping the spring. Rolling movement of the springs is to be preferred, especially during the retraction of the springs 200. Upon return of the springs 200 to their embracing position about the pressers 111 after smoothing down the flippers 801 of the beads, the rods 151 and 152 retract the bead holders and smoothers to their normal position shown in Figs. 8 and 10. The movement of the shafts 30 is not arrested after their first revolution, but continues to again advance the holders and smoothers to the drum ends, as will later appear.

During the retraction of the bead holders and smoothers after setting the beads against the drum shoulders, the contactor disc 718 closes an electrical circuit which energizes the electromagnets or solenoids 351. The armatures 350 of these solenoids actuate the linkages 349 to momentarily withdraw the wedge levers 61d and release the clutch dogs of the clutches 39, thus establishing driving connections between the sleeves 35 and the shafts 29 which rotate the latter for approximately 180°, until the clutch dogs 58 are retracted from the clutch discs 38 by the wedge levers 61e. This half revolution of the shafts 29 rotates the cams 328 and 341 so that the cam rollers 327 and 340 roll about the cam peripheries from the position indicated by the line 806 to the position indicated by the line 807, Fig. 12. This movement of the cams actuates the arms 322, 323, 337 and 338 to move the folders F so that the lips 347 on the folding elements 306 describe a path approximating that shown at 348 in Fig. 17. In Figs. 44 through 46 the action of the folding elements 306 in folding the marginal edge portions of the rubber ply material R about the beads B is shown in successive stages. In Fig. 44 the folder has begun to move through the opening 302 in the end of the drum and the radially inwardly directed edge portions of the ply material which extend beyond the inner circumferential edge 303 of the drum shoulder have been substantially simultaneously engaged around their entire circumference by the rear sides of the folding elements 306. As the folders F continue to be withdrawn by the rods 316, 317, 331 and 332, the cam rollers 340 ride over the high points of the cams 341, causing the folding elements 306 and the bridge or spanning elements 311 to move radially outward, Fig. 45, to fold the edges of the ply material R outwardly and around the beads B. As the folding elements 306 reach their extreme limit of outward radial movement, substantially as shown in Fig. 46, a slight movement toward the drum D is imparted to the folders F by the springs 344 and 345 under the control of suitable depressions in the cams 327 and 341 so as to resiliently press the outwardly folded

edge portions of the ply material over the outer circumference of the beads B by means of the arcuate lips 347 on the folding elements 306 and the spanning elements 311. During the folding of the first layers of the ply material around the beads B, the ply material is pressed against the beads by the folding elements with sufficient force to cause the tacky surface of the ply material to adhere strongly to the tacky surface of the material of the flippers 801 wrapped about the beads. After completion of the folding of the marginal edge portions of the ply material about the beads B, the folders F return through the openings 302 in the ends of the drum D to their normal positions within the latter. Meanwhile the shafts 30, which have completed their first revolution driving the holders H and smoothers S through the initial bead setting operation and the initial smoothing of the flippers 801, as previously described, continue their rotation for a second revolution, the wedge levers 61 being maintained in withdrawn position by the electromagnets or solenoids 160, continuously energized through the disc contactor 715 during the entire folding operation, as previously mentioned. Accordingly, as the folders F are moving within the drum D, the pressers 111 of the bead holders, together with the smoothers S, commence their second movement toward the drum or form.

While the bead holders and smoothers were retracted from the drum after the bead setting and first smoothing operation, the rotation of the gears 145 moved each of the cam followers 144 into that portion of its cam track 143 between the line 805 and line 808 to shift the spiders 117 so that the legs 127 thereof are withdrawn from between the flanges 101 of the cylinders 100 and the legs 112 of the pressers 111. Accordingly, as the pressers advance toward the drum after the folding operation, the bead holding fingers 103 are wholly retracted within the cylindrical pressers, as shown in Fig. 24. On this second forward movement of the pressers 111 the pressure faces 124 thereof simultaneously engage the circumferential portions of rubber ply material R previously wrapped about the beads B by the folders F to press the same against the beads around the entire circumference of the latter, Fig. 47. The increased pressure with which the pressers 111 force the ply material against the rubberized fabric forming the flippers 801 of the beads effects a strong stitching together of the several layers, so that they firmly adhere to one another and are closely compacted.

After the pressers 111 have engaged the ply material on the beads B, continued forward movement of the collars 109 under the influence of the rods 151 and 152 carries the smoothing springs 200 over the outwardly curved edges 206 of the pressers 111 to fold and press the edge portions of the folded ply material against the material of the flippers 801. The helical springs 200, of annular form, move from substantially the full line position shown in Fig. 47 to substantially the broken line position in the same figure and return during this ironing or smoothing action. The smoothing springs simultaneously engage the edge portions of the folded ply material around the entire circumference of the ply material band so that the smoothing and folding action is uniform and even around the entire circumference of the tire band at both ends of the drum or form D.

After the springs 200 have returned to the pressers 111 after the second smoothing and com-

pacting movement, the rods 151 and 152 retract the smoothers S and pressers 111 from the ends of the drum and the rotation of the shafts 30 is arrested by the wedge levers 61. At this time the contactor discs 723, which has been maintaining energization of the holding coil of the relay 734, interrupts the electrical circuit through that coil which deenergizes the motor 733, stopping the control shaft 732. The operator then withdraws from one of the feed spools 606 of the service equipment E another layer or layers of pl. material R and places them or it about the first layers of ply material on the drum D. As previously described in connection with the first plies 802 and 803, subsequent plies indicated at 810 and 811, Fig. 48, may be supplied in the form of a single laminated band or may be supplied as single thickness bands which are successively wrapped about the drum or form D. As in the case of the first plies, the operator may apply the leading end of the band or bands to the drum, pressing the same against the ply 803 so that they adhere due to their inherent tackiness. Upon actuation of the foot switch 790 the drum may be made to revolve slowly as the ply material is withdrawn from the feed spool 606 and wrapped about the drum. After a suitable length has been withdrawn the operator stops the drum and severs the ply material, making the customary joint between the ends of the ply material layer or layers across the drum D. When the third and fourth plies 810 and 811, respectively, have been thus disposed about the drum, the operator then applies the circumferential bands or chaffer strips 618 previously mentioned. The position of these strips is adjacent the edges of the plies 810 and 811, as shown in Fig. 48, and they are substantially evenly spaced around the entire periphery of the outer ply material band.

Closing of the hand switch 735 energizes the relay 734 to start the control motor 733, continued energization of the relay holding coil 736 being maintained through contactor disc 724. Shortly after this starting of the motor 733, the contactor disc 713 energizes the solenoids or electromagnets 443, which actuate the clutches 54, previously described, to rotate the shafts 28 for one revolution which moves the primary pressers P to the center of the drum D where the springs 400 are released by the latch rings 419 to circumferentially embrace the several layers of ply material on the drum and then smooth the same toward the edges of the drum as the pressers are retracted by the rack bars 405 and 406. This movement of the primary pressers P from the central portion of the drum D toward and over the shoulders 205 thereof compacts and presses the several bands or layers of ply material so they firmly adhere to one another and wrinkles or air pockets between the outer layers 810 and 811 are smoothed out toward the edges of the ply material, as also are wrinkles or air pockets between the band or layer 803 and the band or layer 810. As the springs 400 move over the shoulders of the drum or form from approximately the full line position of Fig. 49 to the broken line position of that figure, the marginal edge portions of the outer bands 810 and 811 of the rubber ply material R are simultaneously folded or turned inwardly over the beads B around the entire periphery of the drum or form. This inturning or infolding of the edge portions of the outer band of ply material is effected progressively

from the central portions of the ply material towards the circumferential edges thereof, so that air or gas is forced out from between the first layers of ply material disposed against the drum and the layers 810 and 811. Accordingly, the third and fourth plies are tightly compacted together and against the first and second plies and the bead flippers 801, as shown in Fig. 49. Since the presser springs 400 are in circumferential engagement with the ply material, the folding action is uniform and even around the entire circumference of the drum, therefore avoiding wrinkles or creases and effecting correct and positive radial infolding of the marginal edges of the ply material without circumferential creeping or shifting. As the primary pressers P are retracted to their nominal position, such as shown in Figs. 8 and 10, the contactor disc 724 interrupts the circuit of the holding coil 736 for the relay 734, thus releasing the armature 737 so that the control motor 733 is deenergized, stopping the control shaft 732.

A layer or band of the squeegee stock 614 may then be applied around the central part of the rubberized cord material R previously placed on the drum or form D. This may be accomplished by advancing the movable roller 615 to the surface of the drum, as shown by the broken lines of Fig. 39. The operator then rotates the drum at slow speed by actuation of the foot switch 790 so as to draw the squeegee stock from the supply roll 611 and wrap or place the same about the drum, it being understood that the inherent tackiness of the ply material R on the drum and the squeegee stock 614 is such that they adhere together upon contact. If desired, the squeegee stock 614 may be previously applied to the underside of the tread stock T so that the two are simultaneously applied about the drum D. After a band of the squeegee stock has been placed around the drum D or in the event that the squeegee stock is to be applied directly to the tread, the tread stock T is placed in position as follows:

The operator draws the leading end of the strip of tread stock T from the conveyor 623 and presses the same against the central portion of the outer or fourth ply 811 on the stationary drum D. By actuating the foot switch 790 the drum is then slowly rotated to draw the tread stock T from the conveyor 623 and wrap the same about the layers of ply material R on the drum D. The ends of the tread stock are joined in the usual manner and the operator presses the start switch 735 to again set the automatic control in operation. The circuit in the holding coil 736 is now maintained through the contactor disc 725.

Next, the contactor disc 714 momentarily energizes the electromagnets or solenoids 443 which withdraw the wedge levers 616 from engagement with the clutch dogs of the clutches 51 so that the shafts 28 are driven through one revolution to advance the primary pressers P to the center of the drum D where the springs 400 are released, as previously described, to circumferentially embrace the tread stock T on the drum, as shown by the full lines of Fig. 50. During the retraction of the pressers P the springs 400 tightly embracing the drum and the tire building material disposed thereabout, are drawn toward and over the ends of the drum, as shown by the broken line position of the springs in Fig. 50. During this movement the several plies of cord or fabric material and the layer of tread stock

disposed thereabout are compacted together around the entire circumference of the drum and the squeezing or pressing action is progressive from the center of the drum towards the ends or shoulders thereof. In this manner air or gas and the like, and wrinkles or uneven formations in the tread stock T are ironed or smoothed out so that when the primary pressers P have been retracted the tread stock firmly adheres to the underlying layers of ply material to resist circumferential and lateral shifting during subsequent steps in the completion of the tire.

As the primary pressers are retracted after having circumferentially compacted tread stock T, the contactor disc 727 is in position to effect an electrical connection between its contacts 744 and 745 so that the hand control switch 768 may be manipulated to energize the holding coil 770 of the high speed motor control switch 748. Previously, the contactor disc 26 has broken or interrupted the electrical connection between its contacts 744 and 745 so that the holding coil 711 of the low speed motor control switch 750 cannot be energized therethrough. The contactor disc 703 now establishes an electrical connection which energizes the holding coil 760 of the forward motor control switch 747, setting the main motor 713 in operation to drive the drum D at high speed. While the drum with the assembled tire building materials thereon is thus rotating, the weights 521 and 528 are lowered by the lifts 556, the clutch controlling solenoid 582 having been momentarily energized through the contactor disc 710 so as to connect the members of the clutch 576, which establishes a driving connection for the shaft 568 to rotate the shafts 561 in the manner previously described. The stitcher discs or wheels W, now relatively close together after having been returned to their central position by engagement with the rotating rubber roller 533 as previously mentioned, are raised into contact with the tread stock T on the drum at the center of the latter, as shown by the full lines of Fig. 53. The wheels W are rotated on the threaded shaft 503 by frictional engagement with the tread stock T on the relatively rapidly rotating drum or form, so that the wheels while rolling on the tire building materials disposed about the periphery of the drum or form move progressively toward the ends or shoulders thereof. While the stitcher wheels W are in engagement with the relatively thick central portion or band of tread stock T, they are forced or pressed thereagainst by the combined weight or force of the weights 521 and 528, since the thickness of the tire building materials on the drum prevents the chains 516 from lowering the weights 528 sufficiently to rest on the shoulders 529 of the guide rods. Thus the relatively thick, heavy sectioned portions of the tread material, indicated at 812, are progressively compacted against the ply material on the drum by the rolling action of the wheels W and under the combined force of the weights 521 and 528. As the wheels W move over tapered portions 814 of the tread stock T, the weights are lowered due to the accompanying upward movement of the arms 504, so that the weights 528 are supported by the shoulders 529 of the guide rods and only the force of the weights 521 urges the stitcher wheels W against relatively thin portions 815 of the tread stock T. Accordingly, the present invention, while affording relatively heavy pressure for the localized compacting of

the thick sectioned portion or portions 812 of the tread stock against the ply material, automatically changes the pressure applied to the stitcher wheels as the latter move onto the thin sectioned tread stock material 815 so that excessive pressure is not applied to the latter.

As the stitcher wheels W approach the shoulders of the drum or form D the rubber covered roller 533 is again set in operation by the clutch 538—543 which is actuated through the solenoid 551 energized through the contactor disc 707. Upon movement of the wheels or stitchers W beyond the ends of the drum D, the contactor disc 711 energizes the electromagnet or solenoid 562 so that the wedge lever 61f of the clutch 576 is momentarily withdrawn to permit actuation of the shaft 568 for half a revolution and until the clutch dog is engaged by the wedge lever 61h. This movement of the shaft 568 raises the lifts 566 which move upwardly to support the weights 521 and 528, thus lowering the stitcher wheels W onto the rotating rubber roller 533 which is maintained in operation a sufficient length of time by the contactor disc 707 to return the wheels W to their central position on the threaded shaft 503. Simultaneously with the lowering of the wheels W the contactor disc 707 interrupts the electrical connection energizing the holding coil 760 of the motor control switch so that the motor 13 stops and the drum is brought to rest. Thereupon the contactor disc 716 energizes the electromagnets or solenoids 160, which momentarily withdraw the wedge levers 61 from the clutches 49, permitting the driving of the shafts 30 for a single revolution which moves the holders H and smoothers S toward the drum or form D for the third time during the tire building process. During this movement the gears 145 are driven so that the cam followers 146 each move to that portion of its cam groove 143 between the lines 308 and 306. The spiders 117 are thus rotated on the drums 100 by the movement of the racks 142 under the influence of the cam followers 146 in the grooves 143 so that as the pressers 111 approach the ends of the drum or form D, the extensions 129 of the spiders are positioned beyond the cutaway portions 130 of the collars 109, as shown in Fig. 25. Accordingly, the resilient fingers 103 of the bead holders project well beyond pressure faces 124 of the pressers, further than when positioned to receive the beads B at the start of the tire building process, and engage inwardly directed marginal edge portions 816. Fig. 51, folding the same under the beads B. This folding action of the fingers 103 occurs simultaneously around the entire periphery of the beads so that the inwardly directed edge portions of the third and fourth plies 810 and 811 are folded under the beads by direct radial movement which occurs simultaneously throughout the circumferential length or extent of the edges of the ply material. It is to be noted that the resiliency of the fingers 103 permits yielding thereof during the folding action so that in effect the fingers have a smoothing or stroking action which is highly effective in stitching the tacky layers of ply material together. At the inception of the folding action the ply material is engaged by the sloping surfaces 122 of the fingers, which gently initiate the folding action without injuring the fabric or cord material. During the final stages of this folding movement the pressure faces 124 of the pressers 111 are forced against the chaffer strips 618 over the beads B to tightly compact the same

and the underlying layers of ply material against the beads. Continued movement of the collars 109 over the cylinders 100, after the pressers 111 are against the beads B, in addition to advancing the fingers 103 under the beads, carries the smoothing springs 200 over the curved edges 206 of the pressers 111 and onto the drum D. This smoothing action of the springs 200 occurs simultaneously around the entire periphery of the drum at the ends thereof and compacts the chaffer strips 618 against the underlying layers of ply material. As the rods 151 and 152 retract the collars 109 the springs 200 move off the shoulders of the drum onto the annular pressers 111 and as the latter move away from the beads B the fingers 103 are withdrawn from under the beads, stroking over the folded edge portions 816 of the outer layers of ply material, thus completing the forming of the tire carcass on the drum D.

As the holders H and smoothers S are withdrawn from the drum the contactor disc 719 energizes the solenoids or electromagnets 351 for a short period of time sufficient to momentarily withdraw the wedge levers 61e from the clutches 39 so as to rotate the shafts 29 one-fourth of a revolution, which withdraws the folders F through the openings 302 in the ends of the drum to their positions shown in Fig. 2. Thereupon the contactor disc 705 effects an electrical connection which energizes the holding coil 779 of the main motor reverse control switch 742, setting the motor 13 in reverse operation at high speed, the switch 749 having remained closed after the last stitching operation of the wheels W. Contactor disc 701 then energizes the solenoid or electromagnet 80 which raises the armature 81 to tighten the brake band 78 around the brake wheel 79 on the sleeve 70 so as to collapse the drum or form D. Thereupon the contactor discs 701 and 705 interrupt the electrical connections respectively established thereby so that the motor 13 stops and the brake 78—79 is released. At this time the contactor disc 724 energizes the electromagnet or solenoid 97 which momentarily withdraws the wedge lever 61b from the clutch 95 to actuate the shaft 85 for half a revolution to shift the carriage C to the left as viewed in Fig. 2 to substantially the position shown in Fig. 1, thus permitting the fabricated tire to be withdrawn from the collapsed drum D. Thereafter the contactor disc 725 interrupts the circuit through the holding coil 736 of the relay 734, effecting de-energization of the control motor 733 so that the electrical timing control shaft 732 stops. After removal of the completed tire from the collapsed drum the operator can repeat the cycle or process of tire building just described by again actuating the manual start switch 735.

From the above description it is apparent that the present invention provides a novel method of building pneumatic tire casings and a unique apparatus for carrying out the method. After the assembled casings made in accordance with the present invention are withdrawn from the collapsed drum or form, they are further processed or completed in accordance with conventional tire manufacturing methods. These assembled carcasses commonly referred to in the trade as "green tires," are expanded to approximately the shape of a torus with an inflated air bag disposed internally thereof to retain the shape of the tire and to apply pressure during the vulcanizing process which may be carried out in molds of conventional construction. The

present invention is, of course, directed primarily to the novel method, and the apparatus for carrying out the method, by which the successive layers of ply material and tread are compacted or stitched together, as well as the method and apparatus by which the beads are applied or set and the marginal edge portions of the ply material are folded about the beads.

By uniquely combining in a single machine stitchers, such as the wheels or discs **W** that apply localized pressure to the fabric material, with smoothers and pressers such as the annular helical springs **200** and **400**, which apply an embracing pressure circumferentially around the entire periphery of the tire on the drum, the present invention accomplishes the building of tires in uniform and regular steps of predetermined sequence and timing.

In the manufacture of tires by the use of the present invention production schedules can be established and maintained since the main operations in the fabrication of the tires are performed automatically by machinery that is direct and positive in action. The manual operations required to be performed may be done by relatively unskilled labor since they are of relatively simple nature. Furthermore, the manual operations, because of their simple character, can be performed in periods of time which are substantially the same for successive tires, so that the time for building a tire can be accurately predetermined and carried out in production. While the description of the invention has been made in connection with a tire building machine for forming tires having four layers or plies of cord material, it is contemplated that by suitable modifications of the structure, tires of a greater or lesser number of plies may likewise be built.

The principles and mode of operation set forth above may be altered or modified without departing from the scope of the invention, change being made in the details relating to the construction of the apparatus and the procedure set forth as desired, there being numerous modifications of both the apparatus and the method contemplated.

What I claim is:

1. In the method of building a pneumatic tire which comprises forming a first annular band of ply material, supporting the band in approximately cylindrical shape, forming an annular inextensible bead, folding a circumferential marginal edge of the band around the bead, forming a second annular band of ply material around the first band in overlying relation thereto and with a circumferential marginal edge projecting beyond the fold in the first band, the improvement which comprises simultaneously folding all portions of the projecting edge of the second band in a radial direction around and under the bead and as last named folding progresses resiliently pressing the folded portions of the second band radially outward substantially simultaneously around the entire circumference of the band to compact the same against the bead.

2. In the process of building a pneumatic tire of laminated construction on a form which comprises forming an annular band of ply material about the form and wrapping a layer of tread stock around the band, the improvement which comprises circumferentially embracing the tread stock and resiliently pressing the same against the band and form substantially simultaneously around substantially the entire circum-

ference thereof to effect a primary stitching together of the band and tread stock, and then applying a localized pressure to the tread stock progressively around the circumference thereof to effect a secondary stitching together of the band and tread stock.

3. The method of building a laminated pneumatic tire which comprises forming ply material of unvulcanized rubber into an annular band, supporting the band on a form, applying tread stock of unvulcanized rubber to the band around the entire circumference thereof, circumferentially and resiliently embracing the applied tread stock substantially simultaneously around substantially the entire circumference thereof to compress the same against the ply material to thereby effect primary stitching together of the ply material and tread stock, and rolling a pressing element around the circumference of the tread stock while yieldingly forcing the element toward the form to progressively effect secondary stitching together of the ply material and tread stock.

4. A tire builder comprising a form for receiving ply material and supporting the same in the shape of an annular band, means for supporting a bead having a radial flap and for pressing the bead against a band of ply material on the form, means for folding a marginal edge of a band of ply material on the form over a bead disposed thereagainst, a first smoothing means, a second smoothing means, a driven shaft, driving connections between said shaft and each of said means, said connections being subject to control for making and interrupting the driving connections between the shaft and the several means, and control means for automatically connecting the first smoothing means to the shaft to actuate the same for movement over the form to compact ply material thereon during a predetermined angle of rotation of the shaft, for then automatically connecting the pressing means to the shaft to actuate the same to press a bead against a band on the form during a predetermined angle of rotation of the shaft, for then automatically connecting the second smoothing means to the shaft to actuate the same for movement over the form to stitch the flap of the pressed bead to a band on the form during a predetermined angle of rotation of the shaft, for then automatically connecting the folding means to the shaft to actuate the same to fold the edge of a band around a bead pressed thereagainst during a predetermined angle of rotation of the shaft, and for then automatically reconnecting the second smoothing means to the shaft to actuate the same for movement over the form to compact the folded edge of the band during a predetermined angle of rotation of the shaft.

5. The method of building a pneumatic tire casing which comprises mounting fabric plies upon a tire building drum to provide an annular ply band having spaced, substantially parallel circular edges, circumferentially and resiliently embracing the band on the drum initially adjacent the central portion thereof, and then progressively stroking the band from the central portion toward one edge thereof in a continuous smoothing action which extends entirely around the circumference of the band.

6. The method of building a pneumatic tire casing which comprises supporting an inextensible circular bead against an end of a tire building drum, mounting fabric ply material on the drum to provide an annular ply band having one

edge portion which projects beyond the supported bead and is disposed radially outward of the latter, and folding said edge portion about and under the bead in an operation which is performed simultaneously around the entire circumferential extent of the bead and the edge portion and by resiliently pressing the folded edge of the ply band radially outward against the inside of the bead in a progressive smoothing and axial stroking action that occurs simultaneously about substantially the entire circumferential extent of the bead.

7. The method of building a pneumatic tire casing which comprises mounting fabric ply material on a tire building drum to provide an annular band which has at least one edge portion that overlies an end of the drum, placing an inextensible circular bead against the band on said drum end, folding said edge portion about the bead, mounting additional fabric ply material on the drum over the first mentioned ply material to provide a second annular band which has an edge portion that projects beyond said drum end, and folding said last mentioned edge portion about the bead and the first mentioned edge portion in a movement which takes place simultaneously around the entire circumferential extent of the bead and by resiliently pressing the folded edge of the ply band radially outward against the inside of the bead in a progressive smoothing and axial stroking action that occurs simultaneously about substantially the entire circumferential extent of the bead.

8. The method of building a pneumatic tire casing which comprises placing an inextensible circular bead against one end of a tire building drum, mounting fabric ply material on the drum to provide an annular band which has one edge portion extending beyond the bead, folding the extending edge portion radially inwardly over the bead, pressing the folded band portion against the bead around substantially the entire circumferential extent of the latter to hold the bead against the drum end, and, while so pressing the band portion and holding the bead, folding the band edge under the bead by yielding radial pressure and axial stroking movement.

9. The method of building a pneumatic tire casing which comprises placing an inextensible circular bead against one end of a tire building drum, mounting fabric ply material on the drum to provide an annular band which has one edge portion extending beyond the bead, folding the extending edge portion radially inwardly over the bead, pressing the folded band portion against the bead around substantially the entire circumferential extent of the latter to hold the bead against the drum end, and, while so pressing the band portion and holding the bead, folding the band edge under the bead by yielding radial pressure and axial stroking movement, said last mentioned folding being performed simultaneously around the entire circumferential extent of the bead.

10. In the process of building a pneumatic tire casing on a drum, the improvement which comprises mounting rubber material on the drum in the form of a band, placing a pair of annular pressers initially around the central portion of the mounted material to embrace and radially compress the same, and simultaneously drawing the pressers apart toward the ends of the drum while the pressers resiliently embrace the rubber material to progressively smooth the band against the drum.

11. The method of building a pneumatic tire casing which comprises mounting fabric ply material on a tire building drum to provide an annular substantially cylindrical band which has edges extending axially beyond the drum ends, folding the edge portions of the ply material radially inwardly against the drum ends simultaneously around the entire circumferential extent of the drum, placing inextensible circular beads against the folded edge portions on the drum ends, wrapping said edge portions radially outwardly about the beads simultaneously around the entire circumferential extent of the drum, mounting additional fabric ply material on the drum over the first mentioned band to provide a second annular band having edge portions which project beyond the drum ends, folding said last named edge portions radially inwardly and under the beads simultaneously around the entire circumferential extent of the band edges and the beads whereby distortion of the band occurs uniformly along the entire extent of each of the band edges.
12. A tire builder comprising a base, a building drum mounted on the base for rotation about a horizontal axis, a first set of bead placing and ply smoothing devices and means for actuating the same relative to the drum to perform tire building operations on one end of the drum, a second set of bead placing and ply smoothing devices and means for actuating the same independently, separately and sequentially relative to the drum to perform tire building operations on the other end of the drum, a structure for supporting the second set of devices and the actuating means therefor on the base, and means for moving the structure to bodily shift the same and the devices and the actuating means carried thereby toward and away from the drum and along a path paralleling the rotational axis of the drum.
13. A tire builder comprising a base, a building drum mounted on the base for rotation about a horizontal axis, pairs of bead placing and ply smoothing devices arranged in sets and means for independently, separately and sequentially actuating the pairs for axial movement relative to the drum to perform tire building operations, the actuating means for the sets being synchronized so that the devices of each pair operate in unison, a movable structure on the base for supporting one of the sets, and means for shifting the structure to carry the set of devices supported thereby toward and away from the drum as a unit along a path paralleling the rotational axis of the drum, said actuating means being arranged to retain said synchronous relation during the shifting of the structure.
14. A tire casing builder comprising a base, a pair of spaced supporting structures mounted thereon, one of the structures being movable, a building drum mounted on one of the structures for rotation about a substantially horizontal axis, a set of bead placing and ply folding and smoothing devices carried by each structure, means for independently, separately and sequentially actuating the devices for axial movement relative to the drum and relative to the supporting structures to perform tire building operations on the ends thereof, and means for bodily shifting the movable structure away from the other structure along a path paralleling the rotational axis of the drum to draw one set of devices as a unit away from one end of the drum to permit the removal of a tire casing therefrom.

15. A tire casing builder comprising a base, a pair of spaced supporting structures mounted thereon, one of the structures being movable, a building drum mounted on one of the structures for rotation about a substantially horizontal axis, a set of bead placing and ply folding and smoothing devices carried by each structure, means for independently, separately and sequentially actuating the devices for axial movement relative to the drum and relative to the supporting structures to perform tire building operations on the ends thereof, means for bodily shifting the movable structure away from the other structure along a path paralleling the rotational axis of the drum to draw one set of devices as a unit away from one end of the drum to permit the removal of a tire casing therefrom, and drive means common to both sets of actuating means for operating the same in unison, said drive means including a slip connection associated with the movable structure to maintain synchronism between both sets of devices for all shifted positions of such structure.

16. A tire builder comprising a drum for receiving and supporting band ply material, a pair of ply folding and smoothing devices mounted one at each end of the drum and having actuating means for moving the devices in unison axially of the drum toward and away from the drum ends over predetermined relatively short paths to perform folding and smoothing operations on ply material supported on the drum, and means for independently and separately moving one of the devices axially of the drum over a predetermined relatively long path toward and away from the drum to separate the drum and such device sufficiently to permit withdrawal of a tire therebetween.

17. A tire casing builder comprising a base, a pair of spaced supporting structures mounted thereon, one of the structures being movable on the base toward and away from the other and means for so moving the same, aligned shafts carried by the structures, a tire building drum rotatably mounted on one of the shafts, ply folding and smoothing devices mounted on each of the shafts, and means for moving said devices along the shafts and toward and away from the drum ends to perform folding and smoothing operations on a tire band supported by the drum, said shafts having ends which interfit when the structures are together and which separate when the structures are apart to permit withdrawal of a tire casing therebetween.

18. A tire builder comprising a shaft, a tire building drum on the shaft, a plurality of folding and smoothing devices slidably mounted on the shaft for movement toward and away from one end of the drum and axially thereof, and means for separately and sequentially moving said devices independently and one at a time toward and away from said drum end to successively perform their respective folding and smoothing operations thereon while guided by the shaft.

19. In a tire builder having an open ended circular drum to support a band of fabric with one annular edge of the fabric extending radially across the circular opening in one end of the drum toward the axis thereof, a folder receivable within the drum and having a substantially circular periphery approximating said circular opening in diameter, and means for moving the folder axially of the drum from a position within the latter through said opening to engage the annular edge around substantially the entire cir-

cumference thereof and to fold the engaged edge radially outwardly.

20. In a tire builder having an open ended drum to support a band of fabric with one annular edge of the fabric extending radially across the opening in one end of the drum toward the axis thereof, a folder receivable within the drum and having a substantially circular periphery, a multiplicity of radially movable elements disposed about the periphery of the folder and supported thereby, means for moving the folder axially of the drum from a position within the latter through said opening to engage the annular fabric edge around substantially the entire circumference thereof, and means to move the elements simultaneously radially outward to fold the engaged edge outwardly in a movement which occurs simultaneously around the entire circumference of the band.

21. In a tire builder, an open ended drum, a shaft for supporting the drum for rotation about a substantially horizontal axis, a disc-like folder slidable along the shaft and receivable within the drum, means for folding one edge of a fabric band on the drum radially inwardly to extend across the opening in one end of the drum, and means for moving the folder along the shaft from a position within the drum through said opening to engage the fabric edge substantially simultaneously around the entire circumference thereof and to fold the engaged edge radially outwardly.

22. A folder for a tire building machine comprising a disc-like member mounted for movement along its center axis, a plurality of folding elements mounted on the member for radial movement beyond the periphery thereof, and bridge elements carried between adjacent folding elements and movable therewith to cooperatively provide a substantially continuous circular peripheral edge around the folder for various positions of the folding and bridge elements relative to the disc-like member.

23. A folder for a tire building machine comprising a supporting shaft, a member on the shaft, a plurality of folding elements supported by the member and movable radially with respect to the shaft, a plurality of bridge elements carried between adjacent folding elements and movable therewith to cooperatively provide a substantially continuous circular peripheral edge around the folder, and means movable relative to the member along the shaft and having connection with the folding elements to simultaneously actuate the latter radially.

24. A folder for a tire building machine comprising a supporting shaft, a member on the shaft, a plurality of folding elements supported by the member and movable radially with respect to the shaft, and means having connection with the elements to simultaneously actuate the same so that each element moves in a single direction over an orbital path in a plane through the shaft axis whereby the elements move over material being folded in a single direction only.

25. In a tire builder, a drum having substantially circular openings in the opposite ends thereof, shaft means, means rotatably mounting the drum on the shaft means, a pair of folders having substantially circular peripheries mounted on the shaft means, said folders normally being of less diameter than the drum openings and being movable along the shaft and through said drum openings, said folders each having expandible peripheral portions, and means for moving

the folders away from one another through the end openings in the drum and for then expanding the peripheries of the folders to fold fabric ply material extending across the drum openings radially outwardly and substantially simultaneously around the entire circumferences of the drum openings.

26. A tire builder having an open ended drum to support a band of fabric with one annular edge of the fabric extending radially across the opening in one end of the drum and toward the axis thereof, a folder receivable within the drum and having a substantially circular periphery, means for moving the folder axially of the drum from a position within the latter through said opening to engage the fabric edge around substantially the entire circumference thereof and to commence to fold the engaged fabric radially outwardly, an annular expandable smoother, and means for supporting the smoother for axial movement toward said end of the drum to engage the fabric folded outwardly by the folder substantially simultaneously around the entire circumference of the band and to press the folded fabric against the drum.

27. A tire builder comprising a drum for supporting an annular band of fabric material, means defining a substantially circular end opening in the drum, means for turning a circular edge portion of a supported band radially inwardly over said opening, means for supporting an annular inextensible bead and for placing the same against an inturned band edge on the drum, and a folder having a substantially circular periphery approximating said opening in diameter and movable axially with respect to the drum through the end opening from a position within the drum to engage the turned band edge and to simultaneously fold all portions of the band edge around the entire circumference thereof radially outward about a placed bead.

28. A tire builder comprising a drum for supporting an annular band of fabric material, means defining a substantially circular end opening in the drum, means for turning a circular edge portion of a supported band radially inwardly over said opening, means for supporting an annular inextensible bead and for placing the same against an inturned band edge on the drum, a folder having a substantially circular periphery approximating said opening in diameter and movable axially with respect to the drum through the end opening from a position within the drum to engage the turned band edge and to simultaneously fold all portions of the band edge around the entire circumference thereof radially outward about a placed bead, and an annular smoother having means for moving the same axially with respect to the drum against a folded fabric band edge to engage the same substantially simultaneously around the entire circumference thereof and to press the folded fabric edge against the drum.

29. In a tire builder, a bead holder comprising a support member having a substantially circular periphery and a multiplicity of resilient holding elements secured to said periphery and extending axially therefrom in parallel relation to one another, said elements being disposed in closely spaced side-by-side relation and having free ends adapted to be received within an annular inextensible bead to press outwardly against the latter to frictionally retain the same thereon, and means on the radially outer sides of the elements adjacent the ends thereof for limiting axial

movement of a circular bead embracing the elements.

30. In a tire builder, a drum for supporting a band of ply fabric, an annular elastic and expandable presser, support means for the presser including a multiplicity of pivoted arms each connected to the presser at one end, said arms being movable radially to expand the presser, means for moving the arms axially of the drum to draw the presser over the surface of a ply band supported by the drum, and means for simultaneously pivoting all the arms after withdrawal of the presser from the drum to expand the presser.

31. In a tire builder, a drum for supporting a band of ply fabric, an annular elastic and expandable presser, support means having engagement with spaced points of the presser and actuatable to expand the presser, latch means for holding the support means with the presser in expanded position, means for moving the expanded presser to a position adjacent the center of the drum, means for automatically releasing the latch means upon such movement of the presser whereby the presser contracts by inherent resiliency to embrace a fabric band supported on the drum adjacent the center of the latter, and means for moving the contracted presser from the center toward one end of the drum to progressively smooth and compact the ply band against the drum.

32. In a tire builder having a rotatable drum for supporting a tire band which includes an annular section of thick tread rubber about the center of the band and a thin section of rubber along at least one of the marginal edge portions of the band, a circular rotatable disc supported for bodily movement into frictional engagement with a band on the drum, said disc being mounted for axial movement substantially parallel to the rotational axis of the drum to bear successively against the thick and thin sections of the tire band, and means for urging the disc against the drum, said urging means including a constant pressure means operative during the engagement between the disc and the thin sectioned portion of the band, and a pressure increasing means operative during engagement of the disc with the thick sectioned portion of the band.

33. A tire builder comprising a rotatable drum for supporting an annular tire band having thick and thin annular portions, a threaded rod, a circular stitcher disc threaded on the rod, means for supporting the rod for parallel movement relative to the drum rotational axis toward and away from the drum whereby the disc is moved along the rod upon being rotated by frictional engagement with a tire band on the drum and rides successively over the thick and thin portions of the band, a first weight and means connecting the same to the support means to hold the stitcher disc against a ply band with a predetermined force, and a second weight having connection with the support means to force the stitcher against the tire band with an increased force only during the travel of the stitcher disc across the thick sectioned portion of the band.

34. A tire builder comprising a base, a stationary supporting structure mounted on the base and having folding and smoothing instrumentalities carried thereby, a movable supporting structure mounted on the base and having folding and smoothing instrumentalities carried

thereby, a drum for supporting a tire band mounted for rotation about a substantially horizontal axis and disposed between the folding and smoothing instrumentalities of the stationary and movable supporting structures, said drum being axially extensible to provide for the building of tire bands of different axial lengths, means for shifting the movable supporting structure toward and away from the stationary supporting structure to maintain a predetermined spacing between the ends of the drum and the folding and smoothing instrumentalities, a servicer mounted on the base and having means for supporting a roll of ply material in alignment with the drum so as to be received on the latter, and means for shifting the servicer on the base in a direction parallel to the axis of the drum to center the ply roll with respect to the drum for different length adjustments of the latter.

35. In a tire builder having a rotatable drum and drive means for actuating the same, folding and smoothing instrumentalities operative over the ends of the drum to smooth and fold bands of ply material supported thereon, said instrumentalities being of the type which function only when the drum is stationary and drive means for individually and sequentially actuating the folding and smoothing instrumentalities, a control comprising automatic means operative for intermittently starting and stopping the drive means for the several folding and smoothing instrumentalities, manual means for starting and stopping the drum drive means, and means for rendering the manual control means ineffective during the intervals of time when the automatic means is operative whereby to prevent inadvertent driving of the drum while the instrumentalities are operated over the drum ends by the automatic control.

36. In a tire builder having a rotatable drum for supporting fabric ply bands, means for rotating the drum, pressers for compacting ply material on a drum against the latter, bead holders for placing beads against ply material on the ends of the drum, smoothers for compacting ply material over the placed beads, individual drive means for each of the pressers, holders and smoothers, and a control for regulating the sequential operation of the pressers, folders and smoothers, said control including a shaft and means actuating the same through a single revolution for each tire building cycle of the apparatus, a plurality of elements mounted on the shaft for rotation therewith, and separate means for each drive means responsive to one of the elements for separately controlling the drive means for the pressers, holders and smoothers to retain the operation of the pressing, holding and smoothing instrumentalities in sequential order.

37. In a tire builder having a rotatable drum for supporting a tire band and means for driving the same at multiple speeds, folding and smoothing devices operative in relation to the drum to prepare a tire band on the latter and means for individually actuating the devices, said devices being of the type which function only when the drum is stationary, a control for governing the drive means and the actuating means, said control comprising manually operable means for optionally running the drive means at high or low speed, and automatic means operative for successively operating the several actuating means to run the folding and smoothing

devices sequentially, said automatic means including means for rendering the manually operable means ineffective to run the drive means while the actuating means is operating whereby to prevent inadvertent driving of the drum while the devices are operated over the drum ends by said automatic means.

38. In the flat band process of building a pneumatic tire on a substantially cylindrical drum 10 wherein a circumferential marginal portion of an annular ply band on the drum is folded around the tire bead and against a central portion of the band, the improvement which comprises the steps of first circumferentially embracing the folded portion of the band to compact the same against the drum, smoothing and pressing said marginal portion of the band by stroking the same simultaneously around substantially the entire circumference of the band 15 and over the drum in a direction away from the fold, applying tread stock to the band around the entire circumference thereof, then embracing the applied tread stock initially at a central portion thereof to compact the same against the 20 ply band, and progressively smoothing and pressing said tread stock by stroking the same simultaneously around substantially the entire circumference thereof and initially in a direction from said central portion thereof toward said 25 tire bead.

39. The method of building a pneumatic tire on a substantially cylindrical drum which comprises rotating the drum and placing a ply band thereon while the drum is rotating, stopping the 35 drum and placing a bead against the ply band and folding the marginal edge of the ply band around the bead while the drum is stationary, smoothing and pressing said marginal portion of the band by stroking the same simultaneously around substantially the entire circumference of the band and over the drum in a direction away from the fold while the drum is stationary, rotating the drum and ply band and apply tread stock to the band around the entire circumference thereof during rotation of the drum and 40 ply band, stopping the drum, circumferentially and resiliently embracing the applied tread stock initially at a central part thereof and progressively smoothing and pressing the applied tread stock against the ply band by stroking the same simultaneously around substantially the entire circumference thereof while the drum is stationary, and initially in a direction from said central 45 part of the tread stock toward said bead.

40. In tire building apparatus, a drum and means mounting the same for rotation about a substantially horizontal axis, sets of ply-folding and smoothing devices mounted for operation one over each end of the drum, each folding and smoothing device of the set operative over one end of the drum being paired with a corresponding device of the set operative over the other end of the drum, means supporting one set of devices for relative bodily movement as a unit away from the drum for axial removal of a tire from the latter, and common drive means for actuating the devices of each pair to perform their respective folding and smoothing functions synchronously and in unison and independently of the devices of the other pairs, said drive means being so arranged and connected to the devices as to maintain the synchronous relation between each pair of devices during said bodily movement of the one set of devices.

41. In tire building apparatus, a substantially

cylindrical drum, a first annular elastic presser and means supporting the same for axial movement over the drum to resiliently embrace the latter and thereby compact tire building material thereon, a second annular elastic presser and means for supporting the same in distended substantially circular form, for moving the distended presser axially over the drum to the central part of the latter and then releasing the distended presser to contract circumferentially by inherent resiliency to yieldingly embrace tire building material on the drum, and for then drawing the released presser axially over the drum to progressively compact and smooth the embraced material.

42. In the method of building a pneumatic vehicle tire by the flat band process, the improvement which comprises forming an annular band of ply material and supporting the same so that the major portion thereof is approximately cylindrical with at least one edge turned inward to form a radially directed circular flange, moving a circular bead of less diameter than the band against said flange and co-axial thereto so that an annular marginal edge portion of the flange extends radially inwardly beyond the bead, and folding said marginal portion of the flange radially outward and around the bead to envelop the latter by a substantially simultaneous movement of the entire circumferential extent of the marginal edge of the ply material flange, and pressing the folded part of the flange against the bead as the folding progresses to compact the ply material against the enveloped band.

43. In the method of building a pneumatic vehicle tire by the flat band process, the improvement which comprises forming an annular band of ply material, supporting the band so that the major portion thereof is disposed in approximately cylindrical form with one edge forming an inturned radially inwardly directed circular flange, positioning an annular bead of less diameter than the supported band against a supported portion of said flange by moving the bead axially toward the same so that an annular marginal edge portion of the flange extends radially inwardly beyond the bead, folding said marginal portion of the flange radially outward and around the bead to envelop the latter by a substantially simultaneous radial movement of the entire circumferential extent of the marginal edge of the ply material flange, pressing the folded part of the flange against the bead as the outward folding progresses, and pressing the outwardly folded portion of the flange toward a supported portion of the band beyond the enveloped bead while pressing the bead against the flange.

44. In the method of building a pneumatic tire by the flat band process, the improvement which comprises forming ply material into a first annular band, supporting the band so that the major portion thereof is disposed in substantially cylindrical shape, folding a circumferential marginal edge portion of the band radially outwardly substantially simultaneously around the entire circumference thereof to provide a circular edge fold, forming ply material into a second annular band and placing the same in overlying relation about the first band, and simultaneously folding all portions around the entire periphery of one circumferential edge of the second band radially inward, and around under the circular edge fold of the first band to embrace the same.

45. In the method of building a pneumatic tire by the flat band process, the improvement which comprises forming ply material into a first annular band, supporting the band so that the major portion thereof is disposed in substantially cylindrical shape, folding a circumferential marginal edge portion of the band radially outwardly substantially simultaneously around the entire circumference thereof to provide a circular edge fold, forming ply material into a second annular band and placing the same in overlying relation about the first band, simultaneously folding all portions around the entire periphery of one circumferential edge of the second band radially inward, and around under the circular edge fold of the first band to embrace the same, and pressing the folded part of said second band edge radially outward against the ply material of the first band as the inward folding progresses to compact the folded edge portion of the ply bands together substantially simultaneously around the entire circumferential extent of the bands.

46. The method of building a pneumatic tire casing which comprises mounting fabric plies upon an annular tire building form to provide a circular band having spaced, substantially parallel edges, forming at least one of the marginal portions of the band into a radial inwardly directed circular flange, placing an annular inextensible bead ring of less diameter than the band against the flange by moving the ring axially to the flange and so that the bead ring extends axially beyond the ply band, and folding the edge portion of the flange about the bead substantially simultaneously around the entire circumference thereof and while the form is substantially stationary by a smoothing action initiated across the radially inner side of the bead ring and continuous therefrom in a radial outward direction over one side of the bead ring.

47. A tire builder comprising a supporting structure, a form mounted on the structure for receiving ply material and supporting the same in the shape of a circular band, means for receiving a circular inextensible bead having a radially disposed flap and for moving the bead axially against a band of ply material on the form to locate the bead in predetermined position on the ply band and concentric thereto, means for folding a marginal edge of a band of ply material on the form over a bead located thereagainst, a driven shaft journaled in the supporting structure, means providing a driving connection between the shaft and the bead locating means for actuating the latter and including a first clutch, means providing a driving connection between the shaft and the folding means and including a second clutch, and control means operative automatically to actuate the clutches successively for driving the bead-locating means from said shaft only during a predetermined number of degrees of rotation of the shaft to initially locate the bead and for then driving the folding means from said shaft only during a predetermined number of degrees of rotation of the shaft to fold the ply material about the bead.

48. In a tire builder having a supporting structure, a form mounted on the structure for receiving ply material and supporting the same in the shape of an annular band, individual means carried by the structure for separately placing a circular bead against ply material on the form, folding the ply material around a placed bead, and smoothing material on the drum, a driven shaft

journalized in the structure, means for separately connecting the bead placing means, the folding means, and the smoothing means to the shaft to be individually actuated thereby, and control means governing the several connecting means automatically to connect each of the bead placing means, the folding means, and the smoothing means to the shaft only during separate and predetermined numbers of degrees of rotation of the shaft.

49. In a tire builder having a drumlike form for supporting an annular band of ply material, a combination device operable simultaneously about substantially the entire circumferential extent of a supported band and comprising a generally circular bead-pressing means and means mounting the same for axial movement toward and away from one end of the form, a generally circular bead-supporting and ply-stroking means disposed within the pressing means in concentric relation thereto and mounted for movement toward and away from said end of the form, and actuating means for said device to first move the pressing means and the supporting means in unison and in one predetermined relationship toward said form end to place a circular bead carried by the supporting means against ply material extending over the form end, to withdraw the pressing means and the supporting means from said form end, and to thereafter move the pressing means and the supporting means in unison and in another predetermined relationship toward said form end to apply only the pressing means to the placed bead.

50. In a tire builder having a drumlike form for supporting an annular band of ply material, a combination device operable simultaneously about substantially the entire circumferential extent of a supported band and comprising a generally circular bead-pressing means and means mounting the same for axial movement toward and away from one end of the form, a generally circular bead-supporting and ply-stroking means disposed within the pressing means in concentric relation thereto and mounted for movement toward and away from said end of the form, and actuating means for said device to first move the pressing means and the supporting means in unison and in one predetermined relationship toward said form end to place a circular bead carried by the supporting means against ply material extending over the form end, to withdraw the pressing means and the supporting means from said form end, to thereafter move the pressing means and the supporting means in unison and in another predetermined relationship toward said form end to apply only the pressing means to the placed bead, and to then move the pressing means and the supporting means in unison and in still another predetermined relationship toward said form end to carry the supporting means under the bead in a ply-folding operation and to place the pressing means against the bead in a ply-compacting operation.

51. In a tire builder having a drumlike form for supporting an annular band of ply material, a combination device operable simultaneously about substantially the entire circumferential extent of a supported band and comprising a generally circular bead-pressing means and means mounting the same for axial movement toward and away from one end of the form, a generally circular smoothing means disposed about the pressing means in concentric relation thereto and

5 mounted for axial movement toward and away from said end of the form, a generally circular bead-supporting and ply-stroking means disposed within the pressing means in concentric relation thereto and mounted for axial movement toward and away from said end of the form, and actuating means having operative connection with said device to first move the pressing means and the supporting means in unison and in one predetermined relationship toward said form end to place a circular bead carried by the supporting means against ply material extending over the form end, to then move the smoothing means in embracing relation over said form end for compacting ply material thereon, and after withdrawal of the pressing means, the supporting means and the smoothing means to move the pressing means and the supporting means in unison and in another predetermined relationship toward said form end to apply only the pressing means to the placed bead.

52. In a tire builder having a drumlike form for supporting an annular band of ply material, a combination device operable simultaneously about substantially the entire circumferential extent of a supported band and comprising a generally circular bead-pressing means and means mounting the same for axial movement toward and away from one end of the form, a generally circular resilient smoothing means disposed about the pressing means in concentric relation thereto and mounted for axial movement toward and away from said end of the form, a generally circular bead-supporting and ply-stroking means disposed within the pressing means in concentric relation thereto and mounted for axial movement toward and away from said end of the form, and actuating means having operative connection with said device to first move the pressing means and the supporting means in unison and in one predetermined relationship toward said form end to place a circular bead carried by the supporting means against ply material extending over the form end, to then move the smoothing means in embracing relation over said form end for compacting ply material thereon, to withdraw the pressing means, the supporting means and the smoothing means from said form end, to move the pressing means and the supporting means in unison and in another predetermined relationship toward said form end to apply only the pressing means to ply material folded about the placed bead, and to then move the smoothing means against the form end to compact said folded ply material thereagainst.

53. In a tire builder having a drumlike form for supporting an annular band of ply material, a combination device operable simultaneously about substantially the entire circumferential extent of a supported band and comprising a generally circular bead-pressing means and means mounting the same for axial movement toward and away from one end of the form, a generally circular resilient smoothing means disposed about the pressing means in concentric relation thereto and mounted for axial movement toward and away from said end of the form, a generally circular bead-supporting and ply-stroking means disposed within the pressing means in concentric relation thereto and mounted for axial movement toward and away from said end of the form, and actuating means having operative connection with said device to first move the pressing means and the supporting means in unison and in one predetermined relationship toward said form end

to place a circular bead carried by the supporting means against ply material extending over the form end, to then move the smoothing means in embracing relation over said form end for compacting ply material thereon to withdraw the pressing means, the supporting means and the smoothing means from said form end, to move the pressing means and the supporting means in unison and in another predetermined relationship toward said form end to apply only the pressing means to ply material folded about the placed bead, to then move the smoothing means against the form end to compact said folded ply material thereagainst, and to then move the pressing means and the supporting means in unison and in still another predetermined relationship toward said form end to carry the supporting means under the bead in a ply folding operation and to place the pressing means against the bead in a ply-compacting operation.

54. In a tire builder having a drumlike form for supporting an annular band of ply material, a combination device operable simultaneously about substantially the entire circumferential extent of a supported band and comprising a generally circular bead-pressing means and means mounting the same for axial movement toward and away from one end of the form, a generally circular resilient smoothing means disposed about the pressing means in concentric relation thereto and mounted for axial movement toward and away from said end of the form, a generally circular bead-supporting and ply-stroking means disposed within the pressing means in concentric relation thereto and mounted for axial movement toward and away from said end of the form, and actuating means having operative connection with said device to first move the pressing means and the supporting means in unison and in one predetermined relationship toward said form end to place a circular bead carried by the supporting means against ply material extending over the form end, to then move the smoothing means in embracing relation over said form end for compacting ply material thereon, to withdraw the pressing means, the supporting means and the smoothing means from said form end, to move the pressing means and the supporting means in unison and in another predetermined relationship toward said form end to apply only the pressing means to ply material folded about the placed bead, to then move the smoothing means against the form end to compact said folded ply material thereagainst, and to then move the pressing means, the supporting means and the smoothing means toward said form end with the pressing means and the supporting means moving in unison in still another predetermined relationship, to carry the supporting means under the bead in a ply-folding operation, to place the pressing means against the bead in a ply-compacting operation, and to carry the smoothing means against and over the form end in a ply-compacting operation.

55. In a tire builder having a supporting structure and a form mounted on the structure for receiving ply material and supporting the same in the shape of an annular band, the combination of a device operable simultaneously about substantially the entire circumferential extent of a supported band and including a generally circular pressing means and a generally circular supporting means mounted in concentric relation for simultaneous axial movement to and from one end of the form and actuating

means operable cyclically for successively so moving the device with the pressing means and the supporting means in different predetermined axial relation on successive movements toward the form end during each cycle, means mounted on the structure for folding a marginal edge of a supported ply band about a circular bead disposed against said form end, and means synchronized with said device for actuating the folding means to perform a folding operation on a ply band edge while said device is withdrawn from the form end and during a predetermined part of the cycle of operation of the device.

56. In a tire builder having a ply-supporting drum and in combination with an expandable means movable in a generally radial direction from within said drum to fold a marginal edge of a ply band carried on the drum about a circular bead disposed against one end of the drum so that the edge of the ply band extends radially out from the bead round the entire circumference thereof, a device comprising a substantially circular presser and a substantially circular smoother mounted concentrically about the presser, and actuating means having connection with the folding means and with said device and automatically operable to first move the folder to perform said folding operation and immediately thereafter to move the device axially toward said drum end to carry the presser against the drum to compact said ply band edge against the drum substantially simultaneously around the entire circumference of the ply band while the bead is held in position by the presser.

57. In a tire builder having a ply supporting drum provided with ends to receive circular beads, the combination of means movable along the drum and then over one end thereof for folding a marginal edge portion of ply material on the drum radially inward over said drum end and over a bead received against the drum end so that the edge of the ply band extends inward beyond the bead around the entire circumference thereof, and a device comprising a substantially circular presser and resilient means of substantially circular extent mounted concentrically within the presser, and actuating means having connection with the folding means and with said device and automatically operable to first move the folder to perform said folding operation and immediately thereafter to move said device axially toward said drum end to carry the presser against the covered bead and the resilient means within the bead to fold said edge of the ply band under the bead substantially simultaneously around the entire circumference of the bead.

58. In a tire builder having a ply-supporting drum provided with ends to receive circular beads, the combination of means movable along the drum and then over one end thereof for folding a marginal edge portion of ply material on the drum radially inward over said drum end and over a bead received against the drum end so that the edge of the ply band extends inward beyond the bead around the entire circumference thereof, and resilient means of substantially circular extent mounted coaxially to the drum for movement to and from the drum, and actuating means having connection with the folding means and with the resilient means and automatically operable to first move the folder to perform said folding operation and immediately thereafter to move the resilient means axially toward the drum end to carry the resilient means

within the bead and thereby fold said ply band edge under the bead substantially simultaneously around the entire circumference of the bead, said resilient means being of such diameter that the movement thereof within the bead causes the resilient means to yield radially and to exert a radial pressure outward against the bead.

59. In a tire builder having a circular form of generally cylindrical shape with a curved shoulder and an inturned flange at one end thereof, said flange defining a circular opening in said end of the form and the form being mounted for supporting an annular ply band and a circular bead with the bead disposed against said flange at said one end of the form and with a marginal edge of the ply band extending radially inward over said curved shoulder

at the form end and over the bead, resilient means of substantially circular extent mounted coaxial to the form for movement to and from the latter, said means being of less diameter than the form and of sufficiently large diameter to engage ply material extending radially inward beyond the bead and fold such engaged ply material under the bead substantially simultaneously around substantially the entire circumference of the bead, said resilient means being of such diameter that the movement thereof within the bead causes the resilient means to yield radially and to exert a radial pressure outward against the bead, and means for actuating said resilient means to engage inwardly extending ply material and fold the latter under the bead.

WALTER J. BRETH.

CERTIFICATE OF CORRECTION.

Patent No. 2,313,035.

March 9, 1943.

WALTER J. BRETH.

It is hereby certified that error appears in the printed specification of the above numbered patent requiring correction as follows: Page 25, first column, line 34, claim 42, for "band" read --bead--; and that the said Letters Patent should be read with this correction therein that the same may conform to the record of the case in the Patent Office.

Signed and sealed this 1st day of June, A. D. 1943.

Henry Van Arsdale,
(Seal) Acting Commissioner of Patents.
